APPARATUS FOR OPERATING UPON RUBBER-STOCK AND LIKE MATERIAL

Ernest W. Stacey, Beverly, Mass., assignor to
United Shoe Machinery Corporation, Paterson,
N. J., a corporation of New Jersey

Application February 1, 1932, Serial No. 590,109

164 Claims. (Cl. 12—24)

My invention relates to apparatus for operating upon such material as sheet-rubber and is particularly concerned with the production of soles for footwear. Certain features of the unreeeling mechanism disclosed herein are covered by claims in an application for Letters Patent of the United States for improvements in Systems for delivering sheet material, filed in my name on December 16, 1930 and bearing the Serial No. 502,739. This application matured on December 25, 1934, into Patent No. 1,985,524. Divisional applications, directed to the web-supplying means and to the driving mechanism of the present case, were filed on April 3, 1933, these 10 bearing the respective Serial Numbers 664,190 and 664,189.

An object of this invention is to cut soles or other work-pieces from an extended strip or web of material, with or without the impression upon 20 said pieces of figures or designs, the operations being performed upon the stock rapidly, accurately and in a generally effective manner.

For the attainment of this object, I provide apparatus having, in the illustrated embodiment 25 of the invention, unreeeling mechanism by which the web of rubber or other stock is supplied to feeding mechanism for such operating means as cutting mechanism in which a cutting device co-operates with a pattern during active and in- 30 active periods and which severs the soles or work-pieces from the stock, and, when desired, embossing mechanism, which impresses a design upon the soles. The feeding means advances the stock step by step in proper time-relation 35 for the actions upon it. To relieve the more or less weak and flaccid stock from strain in its delivery, it is illustrated as unwound from a supply-reel by means operating independently of the feeding means, as by means governed by 40 the stock itself. The unreeeling action is thus rendered independent of the length of the feeding steps, which change with the size of the soles produced. The embossing or impression mechanism has a die, which may be opposed by a co- 45 operating platen, said die being arranged for mounting upon either side of the strip. I provide for variations in the space between the cutting and design-producing mechanisms longitudinally of the line of feed to correspond to the 50 length of the feeding steps and therefore to the size of the soles produced, and also a variation transversely of the line of feed to locate the design in the desired areas transversely of the strip or longitudinally of the soles. Adjustable 55 guiding means is also preferably furnished to

insure the proper presentation of strips of stock of different widths to the operating mechanisms, the engagement of the guiding means being with the opposite edges of the stock. The feeding mechanism preferably includes separate strip-advancing means, shown as a rotatable feeding roll and a traveling feed-belt, upon the latter the cutting operation being performed. At the cutting mechanism, the stock is illustrated as clamped upon the belt between a pattern for 10 determining the contour of the piece produced and an opposed pressure device. The cut pieces are caused to adhere to the belt under the influence of the pressure, and the scrap guided away from said belt. The work-pieces may consequently be separated readily from the scrap and collected conveniently.

Among the novel features which are embodied in the illustrated apparatus and contribute to its efficiency are the following, it being understood that in each instance the arrangement disclosed represents but one of the several embodiments which the particular phase of the invention may assume: The organization of the feeding mechanism, this having one section including adjustable means for guiding the stock and a second section furnished by a belt for supporting the stock during the cutting operation and being variable as to tension; the actuating means for such a belt whereby it may be advanced by steps of different lengths to facilitate the economical production of work-pieces of diverse sizes; embossing mechanism with provision for actuating and adjusting it in a plurality of directions for different work-sizes; the way in which the stock is gaged to position it at the beginning of operation of the apparatus; the patterns provided with oppositely inclined surfaces and being reversible for the cutting of both right and left soles; the mounting of the patterns to permit them to be changed readily and retained firmly; the support and yieldable operation of the pressure device which co-operates with the pattern; the manner of maintaining the stock in the proper relation to the cutting mechanism and insuring its advance by the feeding means; the employment of interchangeable patterns and cutting devices; the means by which the path of the traveling knife or other cutting device is caused to closely conform to the pattern; the provision of means for resisting the movement of the knife out of the plane of the pattern; the way in which a force is adjustably exerted to urge the knife into co-operation with the pattern for cutting, and the knife held clear 55

of the pattern for changing said knife; the automatic movement of the knife into and out of cutting relation to avoid injuring the work for a certain type of cut; the manner in which the knife is mounted, co-operates with and is guided by the pattern; and the heating of the knife to facilitate cutting and the separation of the cut pieces and scrap.

The accompanying drawings illustrate a particular embodiment of my invention, including two forms of the cutting mechanism. In these drawings,

Figs. 1 and 2, placed with the sheets end to end and Fig. 1 at the left, show the entire apparatus in broken side elevation;

Fig. 3 is a vertical sectional detail illustrating the actuating means for the stock-feeding belt;

Fig. 4 is a broken end elevation of the unreeling mechanism viewed from the right of Fig. 1;

Figs. 5 and 6 are fragmentary perspective views of said unreeling mechanism;

Fig. 7 is a sectional detail upon the line VII—VII of Fig. 5;

Figs. 8 and 9 are similar views upon the line VIII—VIII of Fig. 6 and line IX—IX of Fig. 5, respectively;

Fig. 10 is an enlarged vertical transverse section on the line X—X of Fig. 2;

Fig. 11, a full vertical longitudinal section on the line XI—XI of Fig. 10;

Fig. 12, an enlarged broken side elevation of the drive-controlling mechanism;

Fig. 13, a broken plan of said mechanism;

Figs. 33 and 34 are sectional details of the knife-holder and knife on the lines XXXIII—XXXIII and XXXIV—XXXIV, respectively, of Fig. 31;

Fig. 35 (Sheet 2) is a bottom plan view of an inside-bevel sole cut and embossed by the apparatus; and

Fig. 36 is a transverse section on the line XXXVI—XXXVI of Fig. 35.

The illustrated apparatus includes six co-operating mechanisms, appearing in Figs. 1 and 2.

The first of these, designated as A, unreels web-material, as rubber stock with a design previously formed upon one side from which soles or other work-pieces are to be cut, the delivery being so controlled that the material is presented to the succeeding intermittently acting feeding mechanism B without being subjected to stresses produced by drawing it from the reel. The unreeled material is advanced by the feeding mechanism, and, while still in web-form, is subjected to the action of embossing mechanism C, which produces upon the areas from which the soles are to be cut such designs as trade-marks and size-designations. Cutting mechanism D, with which is associated a portion of the feeding mechanism, 5 severs the soles one by one from the web, this being in effective operation during periods of rest of the feeding mechanism. Separating and conveying mechanism E removes the cut pieces and scraps from the cutting mechanism by separate 10 paths. The apparatus, save for the unreeling mechanism A which is independently actuated, receives power from driving mechanism F (Fig. 15). 15

Specific examples of the work which my improved apparatus is adapted to perform are furnished by two types of rubber soles. One of these, designated as S, is illustrated in Figs. 35 and 36 and may be said to have an inside bevel about its periphery. That is, the edge is inclined 20 at T downwardly and outwardly toward the tread-surface. When such a sole is attached to a shoe-bottom with the thin margin turned up and cemented to the foxing-area, there is produced what is commonly called a rolled edge, the 25 initially beveled surface being rounded outwardly from the tread. The other type of sole has an outside bevel, the inclination being downward and inward to the tread. This, cemented to a shoe-bottom, gives the effect known as a straight edge 30 or one which is nearly vertical to the tread. Both types of soles ordinarily have over the forepart a roughened area U, and at the heel a similar, thicker area V. Between these is a shank-portion 35 W thinner than either, upon which are embossed a trade-mark X and a size-number Y. In the preferred embodiment of my invention, the inside bevel for the rolled-edge sole is produced by the mechanism D as illustrated in Figs. 35 and 20 to 26, inclusive, in which a cutting device or knife K penetrates the stock from above, being inclined downwardly and inwardly beneath the sole-area to undercut. For the formation of an outside bevel, giving a straight-edge sole by overcutting, a knife N is inclined downwardly and 40 outwardly, as appears in Fig. 31. If, because of any preference on the part of a manufacturer based, for example, on factory practice or arising from the nature of particular work, it is not desired to shift the knives and their carriers when 45 the type of sole changes, either of such mechanisms, preferably the overcutting arrangement with the knife N, may be employed for both the inside and outside bevels, the relation of the tread-surface of the stock being reversed to present its pattern-surface either at the upper or the under side. In this connection, the elements of the embossing mechanism C are arranged to be correspondingly reversed. In its capability of 50 thus being differently organized, the illustrated machine is adapted to suit varying conditions and preferences although, as indicated, it is believed that for best results, ordinarily at least, the machine should be operated in the manner first set forth.

Referring particularly to Figs. 1 and 4 to 9, inclusive, the unreeling mechanism A is shown as carried upon a wheel-truck or base 30, which is aligned with a frame 32 supporting the other mechanisms. From the base rises a frame consisting of spaced vertical uprights 34, 34 and upwardly and inwardly inclined members 36, 36, together with whatever tying and bracing members may be desirable. At the opposite junctures 10 of the frame members 34 and 36 are bearings 38, upon which rotate the spindles of a reel 40, the freedom of rotation of which may be governed by a spring-actuated brake 37 bearing upon the periphery of one of the cheeks of the reel. This reel, when supplied to the apparatus, contains a coil of material R to be operated upon, this, in the present instance, being a continuous web of rubber stock. Since this stock, when freshly calendered, is relatively soft, the convolutions of 20 the coil are held out of contact with one another by separating means, here shown as two in number. One of these designated as L, is of the type disclosed in Letters Patent of the United States No. 1,838,792, dated December 29, 1931, and having spaced transverse slats 39 extending between sprocket-chains 41. This furnishes a spiral cell, in which the material is held without substantial pressure upon its opposite faces. I prefer to further protect the stock by winding with it a web 30 of textile material or liner, this guarding the stock at its inner side against indentation by the slats of the separator L.

As the stock is advanced by the feeding mechanism B to the embossing mechanism C and cutting mechanism D, it is unreeled by forces applied to the separators only as it is required, the time of this action being determined by the condition of a slack loop depending at r between the mechanisms A and B. For this purpose, the 40 chains 41 of the separator L are engaged by sprocket-wheels 42, 42 fast upon a horizontal shaft 44 rotatable in brackets mounted upon the frame members 36. This shaft is joined by a chain 46 of spur-gearing and a friction device 47 (Fig. 7) to a countershaft 48 journaled across the frame members 36, said countershaft receiving power from a motor 50 upon the base 30 through belt-gearing 52, a friction-clutch 54 (Fig. 9), reduction-gearing contained within a casing 56 and sprocket-gearing 58. As the separator L is drawn off by the rotation of the sprocket-wheels 42, it is wound upon a reel 60, the spindle of which turns in bearings 62 upon the uprights 34. Rotation is imparted to the reel 60 to coil upon it the separator L by grooved rolls 64, 64 rotatable upon arms 66 arranged to turn about the shaft 48, from which shaft the rolls are driven through sprocket-gearing 68. Springs 69 connecting the arms and frame draw the rolls 64 into driving engagement with the reel 60. For convenience in removing and replacing this reel, there is illustrated means for temporarily drawing the rolls 64 away from the reel-cheeks with which they contact. This means may consist of 55 a crank-shaft 70 journaled across the frame above the rolls 64 and having its cranked portions joined to the arms 66 by links 72. An actuating crank 74 may be turned by the operator through such an angle that the rolls will be elevated to free the reel, the parts being held in this relation until restored by the operator by engagement of the crank with a fixed pin 76 on the frame.

At the same time the separator L is drawn off, as just described, the liner l is wound upon a

core 78 supported by the squared inner ends of opposite spindles 80 and 82 rotatable in bearings in the frame below the shaft 44. The spindle 80 is turned by sprocket-gearing 84 from the shaft 44 through a friction device 86 (Fig. 8). To facilitate the removal and replacement of the core, the spindle 82 is longitudinally movable in its bearing 88 to separate it from the opposite spindle, being releasably held in its core-supporting position by a latch 90 pivoted upon the bearing 88 and entering a circumferential groove in the spindle. Moreover, this bearing is trunnioned upon the ends of screws 92, so it may be turned about a vertical axis and thus allow the core to be swung out of alignment with the spindle 80. After releasing the latch, the spindle 82 may be slid through its bearing to the left (Fig. 4) until the core is free from the spindle 80, and then the spindle 82 and the core turned upon the trunnions. This permits the core to be removed without interference.

To control the unreeling of the stock R by force applied to the countershaft 48 as determined by the condition of the loop r of stock, there is situated above the center of this loop a roll 94 upon the end of a long substantially horizontal lever-arm 96 projecting from a fulcrum-shaft 98 turning in the frame. A short arm 100, fast upon the fulcrum-shaft, extends above the upper extremity of a vertical rod 102 mounted to reciprocate upon the gear-case 56 (Fig. 5). The lower end of the rod rests upon a horizontal arm of a lever 104, a vertical arm of which actuates the movable member of the clutch 54. As appears in Fig. 1 of the drawings, when there is a substantial length of the stock in the loop r, so the feeding mechanism B may draw from it without the necessity for unreeling additional stock, the loop hangs clear of the roll 94, and the weight of the lever-arm 96 removes the arm 100 from the rod 102. The clutch 54 at this time slips, and the unreeling system is at rest. This continues until the advance of the stock for embossing and cutting raises the loop against the roll, turning the arms 96 and 100 anti-clockwise (Fig. 1). This, with the requirement of small expenditure of energy, because of the excess of length of the arm 96 over the arm 100, forces down the rod 102, actuating the lever 104 to produce engagement of the clutch 54. The shaft 48 is thereby rotated and, through the gearing 46, turns the sprocket-wheels 42. These, by their action upon the chains 41 of the separator L, rotate the reel 40 to draw therefrom the separator and stock, the latter lengthening the loop r and freeing the controlling elements to release the clutch 54 and stop the unreeling. During this delivery of the stock, the separator L is being simultaneously wound upon its reel 60 by the action of the rolls 64, the friction 47 slipping as the coil accumulates. In the same manner, the liner l is coiled upon the core 78, and its increasing diameter is compensated for by the slipping of the friction 86. The reels 40, 60 and 78 are simultaneously controlled in their action by their connection to the countershaft 48. This goes on until the stock R upon the reel 40 has become exhausted. The empty stock-reel and the two coils of separator are thereupon removed from their supports and replaced by a full reel 40 and empty reel's 60 and 78, and the unreeling operation repeated.

The feeding mechanism B is shown as in two sections. Journalized in brackets across the incoming end of the frame 32 is a feeding roll 110 (Figs. 2 and 11), which draws forward the un-

reeled stock, elevating it from the loop *r*. An idler-roll *112*, rotatable below the roll *110*, is so located as to increase the peripheral engagement of the stock with the feed-roll, and also serves to guide the stock to determine the lateral position of the web with respect to the embossing mechanism *C* and cutting mechanism *D*. For the latter purpose, the roll *112* has guide-flanges *114*, *114* (Fig. 27) adjustably secured upon it by screws *116*, which draw divided portions of the flanges together. These flanges, positioned as desired longitudinally of the roll for webs of different widths, contact with the edges of the web being fed and retain it in the correct path. From the roll *110* the stock proceeds along a horizontal table *118* at the top of the frame *32* through the embossing mechanism *C* and upon a feeding belt *120*, which, in addition to advancing the stock, provides a surface upon which the mechanism *D* makes its cut. At one side of the table *118* is a vertical gage-wall *117* (Figs. 11 and 27) to assist the roll-flanges *114* in alining the stock. At the entrance-end the wall may be provided with an overhanging stock-retaining flange, and both the wall and flange are shown as having inclined throat-portions. By slot-and-screw connections *119*, the wall *117* may be adjusted toward and from the path of the stock upon the table to best position it for the particular width being operated on. The belt *120*, of rag-stock or other relatively soft penetrable material, operates over a driving roll *122* and a guide-roll *123*, these having shafts *124* and *125*, respectively, journaled horizontally in the frame *32*. A horizontal run *126* of the belt between these rolls supports the stock for each cutting operation, and then advances it to present another area to the cutting mechanism. From the rolls *122* and *123*, the belt *120* passes about a lower guide- and tension-roll *128*, its path being generally triangular. The roll *128* is rotatable about a spindle *130* carried at the lower extremities of slide-rods *132*, *132* (Fig. 10) arranged to move vertically in the frame. Each rod is provided with a longitudinal series of rack-teeth *134*, with which meshes a pinion *136*, these pinions being respectively fast upon the ends of shaft-sections *138* and *140* journaled at opposite sides of the frame and horizontally alined with each other. The inner ends of both shaft-sections are surrounded by a sleeve *142*, and about the section *140*, at the end of the sleeve, is a collar *144* having at its inner side a circumferentially elongated depression *146* arranged to receive a projection *147* from the adjacent side of the sleeve. Encircling the shaft-sections *138* and *140* are torsion-springs *148* and *149*, respectively, secured at their outer extremities to the frame. The inner end of the spring *148* engages a set-screw *150*, which also normally clamps the sleeve *142* to the shaft-section *138*. A similar set-screw *152* in the collar *154* is engaged by the spring *149*. It will be seen that the two springs may be caused to act together to rotate the pinions *136* and force down the rods *132*, thus urging the roll *128* against the belt *120* to place it under tension and produce a smooth surface at *126* for the cutting operation. At the same time, because of the capability of relative movement between the shaft-sections through the connection *146*, *147*, the rods may yield independently against the respective springs to compensate for inequalities of the belt across its width. By loosening the set-screws *150* and *152* and applying a wrench to openings *153* in the sleeve, said sleeve and collar may be rotated upon

the shaft-sections to vary the tension of their springs, and the set-screws again tightened to hold this adjustment. When the belt *120* is to be changed, the shaft-sections are rotated together by a crank *154* upon the outer end of the section *138*, this elevating the rods *132* and raising the roll *128* clear of the belt. Here it may be temporarily retained by a latch-pin *156* movable through the frame and entering a depression at *158* in the adjacent rod.

To transmit power from the driving mechanism *F* to the feeding belt *120* and roll *110*, said mechanism has a lever *160*, which is continuously oscillated, as will later appear, upon a short horizontal shaft *162* (Figs. 3 and 10) rotatable at one side of the frame, and which furnishes its fulcrum. Guided for adjustment longitudinally of the curved upper arm *161* of lever *160* is a block *163* joined by a link *164* to an arm *166*. The lever-arm *161* is curved substantially on an arc of which the pivotal connection between the link *164* and arm *166* is a center. Said arm *166*, through a Horton or other one-way clutch *168* carried by the shaft *124*, rotates the roll *122* step by step in one direction to advance the belt *120* and thus the stock through the mechanisms *C* and *D*. From the shaft *124*, sprocket-gearing *170* turns the shaft *125* of roll *123*, while, by way of sprocket-gearing *172*, an idle shaft *174* and sprocket-gearing *176*, the feed-roll *110* is rotated to lift the stock from the loop *r* in steps of the same length as said stock is advanced by the belt *120*.

The length of the feeding steps, and therefore the spacing along the web of the areas from which soles of different sizes may be cut, is determined by the adjustment of the block *163*. As shown in Figs. 2 and 3, the block has, movable in slots formed in it and extending transversely of the lever-arm *161*, a nut *178* to receive a screw *180* arranged to turn upon the lever *160*. The lower end of this screw is joined by bevel-gearing *182* and spur-gearing *186* to a sleeve *188* capable of rotation about the shaft *162* and having integral with it a hand-wheel *190*. Splined to the shaft *162* to move longitudinally thereof, so it may be forced against the hand-wheel, is a collar *191*. The collar and hand-wheel may be clamped together by a hand-nut *192* threaded upon the end of the shaft *162*. The edge of the collar, which is inclined, preferably bears an index-mark *194* (Figs. 2 and 10), along which may move a scale *196* upon the face of the hand-wheel. The scale may be graduated in sole-sizes. With the nut loosened, the hand-wheel may be turned until the size-mark for the sole which is to be produced is brought into registration with the index-mark. Through the gearing *186* and *182*, this will rotate the screw *180* and thus move the block *163* until such a throw is imparted to the arm *166* as to give the correct length of feed-step. The setting having been made, the hand-wheel is locked against rotary displacement upon the shaft by the nut *192*. Since the feed-roll *110* is driven from the shaft of the belt-roll *122*, the extent of movement of which may be altered in the manner just indicated, the rotation of the roll is similarly varied. Therefore, whatever adjustment is made, it affects the two portions of the feed mechanism in the same way, so the web of stock is advanced uniformly. On account of the curvature of the lever-arm *161* and the capacity for relative transverse movement between the block *163* and screw *180*, the shifting of the block along the

lever-arm does not move the arm 166. Consequently in making the feed-adjustment, the operator is not compelled to turn the various elements actuated by said arm 166.

As the stock passes over an opening in the table 118, it comes under the influence of the embossing mechanism C, which is illustrated in Figs. 2, 11, 19 and 27. Arranged to slide in horizontal ways 200 extending longitudinally at one side of the frame 32 is a carriage 202, from which arms 204 extend upwardly into the plane of travel of the stock. Fulcrumed at 206 upon these arms are jaws or pressure-levers 208 and 210, with their inner arms extending respectively above and below the stock. The levers are oscillated oppositely by cams 212 operating in boxes 214 upon the outer extremities of the levers, these cams being splined upon a shaft 216 journaled horizontally in the frame longitudinally thereof and parallel to the path of the stock. The shaft 216 is rotated by a chain of connections to the driving mechanism F, these including bevel-gearing 218 (Fig. 10), a vertical shaft 220 turning at the outside of the frame, bevel-gearing 222 and a horizontal shaft 224. The latter shaft has secured to it a crank 225, which oscillates the feed-lever 160 by engagement with a slot 227 therein (Fig. 3). The inner ends of the levers 208 and 210 are divided vertically at 226, and upon each of these spaced portions are upper and lower ways 228, 228. Upon the ways of each lever a carrier-block 230 is mounted to slide. The upper block may be moved on its ways by a shaft 232 journaled in the arm 208 and threaded into the block at 234. A hand-wheel 236 is provided upon the outer end of the shaft 232, to be turned by the operator for the adjustment of the carrier-block along the lever. At its inner extremity, the shaft 232 is joined by bevel-gearing 238, universal connections 240 and bevel-gearing 242 to a shaft 244 rotatable in the arm 210 and there having threaded engagement with the corresponding carrier-block. These connections cause the upper and lower carrier-blocks to be moved together upon their ways when the hand-wheel 236 is turned, and thus are kept in constant registration with each other. Splined to slide in each block 230 toward and from the opposite block is a tubular stem 246 of a die-holder 248. Each holder may be independently adjusted toward and from the other, to produce proper engagement with the stock of the embossing elements held in them and at the normal plane of feed, by a screw 250 threaded into the stem 246 and arranged to be rotated in the block by a hand-wheel 252 fast upon its outer end. In either holder, one or more dies 254 may be clamped by set-screws 256 threaded into the holders and engaging stems 258 of the dies, which stems enter openings in the holder. For example, a trade-mark-design and a size-designation may be thus mounted, while opposing these in the opposite lever may be similarly mounted a smooth co-operating platen 259. The embossing elements are moved positively, without yield, into engagement with the rubber stock. At the end of the embossing travel the die and platen are separated by a definite space, causing the die to enter the soft rubber to a predetermined distance and to produce a clear impression. After the impression has been made, the stock is freed from the embossing elements by stripper-plates 260 surrounding said elements and yieldably mounted upon the holders. The inversion of these ele-

ments, that is, the location of either the dies or platen upmost, allows the embossing to be done upon the upper or under side of the stock, when a single arrangement of the mechanism D with either the knife K or N is to be used to produce both an inside bevel and an outside bevel. Moving the carrier-blocks and their embossing elements along the levers 208 and 210 by the hand-wheel 236 causes the position of the impression upon the stock to be shifted transversely of the web, and thus the relation upon the soles thereafter cut, to properly locate the designs upon the shank-portion for different size soles.

As the length of the feeding steps of the stock is altered under the control of the hand-wheel 190 to provide for the economical cutting of soles of different widths, the embossing mechanism must be correspondingly adjusted to locate the embossing symmetrically upon said soles. This effect by shifting the levers 208 and 210 bodily longitudinally of the web of stock. The carriage 202 of the embossing mechanism has a threaded connection at 262 with a screw 264 (Fig. 27) arranged to turn horizontally in the frame. Bevel-gearing 266 connects the screw to a horizontal transverse shaft 268 extending to the operator's side of the apparatus and there provided with a hand-crank 270. The crank may be joined to the shaft by a separable projection and depression 272, so normally it may hang loose to avoid accidental displacement of the parts controlled, or may transmit its rotation to the shaft when the projection and depression are in engagement. This rotates the screw 264 to move the carriage 202 toward and from the mechanism D. As the levers 208 and 210 are moved in one direction or the other along the shaft 216 by this travel of the carriage, the cams 212 are shifted with them by contact of a flange 273 formed integrally with them and projecting between the lever-boxes 214. The amount of this movement for a particular width of sole may be indicated by a disk 274 rotatable upon a short horizontal spindle 276 fixed upon the frame, said disk having a graduated periphery, appearing through a sight-opening 278 in the frame (Fig. 2). The disk has fast upon it a worm-wheel 280 meshing with a worm 282 upon the shaft 268, so the disk turns as the setting of the carriage is effected. The correct adjustment is determined by bringing the chosen size-graduation upon the disk into registration with an index-mark 284 upon the frame at the edge of the opening 278.

Associated with the embossing mechanism is a gage member in the form of a pin 290 (Fig. 19) mounted to move vertically through the carrier-block of the lever 208 just at the inner side of the upper embossing element. The pin is situated with its rearward side opposite the center of said element, and is held normally above its face by a spring 292. The feeding mechanism B may be arranged to stop at a half-step when the power is disconnected, or with but half the advance between successive operating areas effected. Consequently, if the operator, in introducing the end of a fresh web of stock, depresses the gage-pin below the embossing element and brings the forward end of the web into contact with it, the apparatus, upon being started, will first complete the half-step of feed. This brings the area for the first sole to be cut into proper position between the die and platen to receive the impression. Since the gage-pin is mounted on one of the carriers 239, it shares with it the adjustment by the hand-crank 270 and hand-wheel 236 for 75

different sole-sizes and is correctly located without individual adjustment.

At the mechanism D, a housing 300 rises above the frame 32, from the top of which housing depends a spindle 302 fixed against movement (Fig. 11). At the lower extremity of this spindle is a head or enlargement 304 elongated transversely of the web of stock (Fig. 10), and from the under face 305 of the head, near its ends, extend two retaining projections 306, 306 (Fig. 28). Each projection has a terminal enlargement 308, at the upper side of which is an inclined surface 310 diverging from the horizontal lower surface of the enlargement. Midway between the projections, a latch-pin 312 is movable vertically in the head, having a tapered end urged normally down below the surface 305 of the head by a spring 314. This spindle-end receives a pattern or templet P lying in a horizontal plane and corresponding in its peripheral contour to the work-piece which is to be cut, it serving as a guide for the knife or cutting member K, which undercuts the stock and which is supported and actuated as will later be described. The pattern has two openings 313, 313, spaced as are the projections 306 but giving considerable clearance to admit these. Within the openings are surfaces 315 corresponding in inclination to the surfaces 310 of the retaining projections. The pattern to be employed is placed against the surface 305 with the openings 313 about the projections 306, and then forced to the right, as viewed in Fig. 28 of the drawings. When the inclined surfaces 315 of the pattern have slid over the surfaces 310 upon the projections until the upper face of said pattern is firmly against the surface 305 of the head, a tapered depression 317 in the pattern will have come into alinement with the tapered end of the raised pin 312. This pin is thereupon released and forced by its spring into the depression, locking the pattern securely to the spindle-head in the correct relation to the web of stock. For the purpose of cutting either right or left soles, I prefer to invert the pattern P, and therefore the surfaces 315 are duplicated, being inclined in opposite directions from the median plane of the pattern. Either of these pairs of surfaces may be brought into co-operation with the surfaces 310 upon the retaining projections, and thus the pattern secured in operating position with either side up. As appears in Figs. 15 and 16, the pattern P is furnished by a generally sole-shaped plate, which may be of metal, it having a vertical peripheral surface 316, a lower inclined peripheral guide-surface 318 and an upper oppositely inclined guide-surface 320. The surfaces 318 and 320 form with each other an external or salient angle.

Co-operating with the pattern and situated at the under side of the stock and belt 120 is a vertically movable pressure device Q (Figs. 10 and 11) acting to clamp the stock against the pattern during the cutting operation. To permit the clamp to more uniformly press against the stock and thus adapt itself to soles varying in thickness, the engaging surface may be furnished by a series of independently yieldable members in the form of bars 322 (Fig. 29) extending longitudinally of the web and guided between spaced walls 324 rising from a back-plate 326 of the clamping device. Springs 328 between the bars and back-plate force said bars normally up, this movement being limited by headed studs 330 passing through counterbored openings in the 75 bars and threaded into the plate. Said plate is

shown as guided for vertical movement by a depending rod 332 operating in an opening in the frame.

To effect the reciprocation of the device Q so it may alternately clamp and release the stock and belt for the successive cutting and feeding operations, the back-plate 326 has depending from it a tubular stem 334, telescoping with which is a plunger 336 having at its lower extremity a head 338. Helical springs 340 are interposed between the plate and head, surrounding rods 342 fixed to the former. The upward movement of the pressure device, under the influence of the springs, is limited by nuts 344 threaded upon the ends of the rods and engaging the under side of the head. Rotatable upon the head is a roll 346 resting on a cam 348 fast upon the shaft 224. The cam is so formed that, when the stock has been advanced through a feeding step and is at rest, it raises the device Q to yieldably force the belt 120 against the stock and said stock against the pattern ready for the cutting operation. The stock may further be held smoothly upon the belt both during the operating and feeding periods by rolls 350 (Figs. 11 and 18) rotatable upon pairs of arms 352, 352 projecting from sleeves 353 arranged to turn about a spindle 354 carried near the bottom of the housing 300 between the embossing mechanism C and cutting mechanism D. Torsion-springs 356, adjustable as to the force exerted, surround the spindle and engage at their upper extremities the arms 352, to urge the rolls toward the stock. The extent of this movement may be adjustably limited by screws 358 threaded through lugs rising from the sleeves, the inner ends of said screws contacting with the housing. Because of the pressure of the stock against the belt 120 by the rolls 350, proper feeding engagement is assured to overcome the resistance offered by the table 118 to advance.

Surrounding the spindle 302 is a sleeve 364, and about this sleeve and having a bearing in the housing is a sleeve 366 (Fig. 11). The two sleeves are rotated in opposite directions by bevel-gearing 368 (Fig. 10) from a horizontal shaft 370, which is driven by bevel-gearing 372 from the vertical shaft 220. The sleeves rotate two driving members for the cutting mechanism. The inner sleeve 364 has secured at its lower end 50 a driving eccentric 374, while the sleeve 366 carries fast upon it, just above the eccentric, a driving crank-arm 376 (Figs. 15, 16, 17 and 18). Surrounding the eccentric, in the form of a strap therefor, is a primary cutter-actuating member 55 378. Rising from an arm projecting from the member 378 is a pin 380 fixed thereto and having rotatable about its upper end a roll 382 movable in a slot 384 extending longitudinally of the arm 376. The effect of the arm upon the pin 60 is to revolve it in a circle, this action being modified, however, by the eccentric 374, which moves the pin back and forth in the slot 384. As a result of this, the axis of the pin follows an elongated closed path, roughly elliptical in character, indicated by the dash-line *a* in Fig. 18, the major axis of the ellipse extending in the same general direction as that of the pattern. Were force applied to the knife or cutter K to carry it in its stock-cutting travel about the pattern P by direct connection to the pin 380, there would be portions of the path of the knife, as at the shank of the pattern, where the force would not act tangentially with respect to the curved edge of the pattern, because of the dif- 75

ference between the paths of the pin and knife. The resistance offered to the movement of the knife would therefore be increased, and the cut less smoothly made. A further modification of the driving effect of the crank-arm over that of the eccentric is therefore produced. Free to turn about the lower extremity of the pin 380 is a secondary knife-actuating member, in the form of a disk 386 rotated constantly by a gear 388 fast upon it and meshing with an idle pinion 390 journaled upon a stud 392 depending from the eccentric-strap 378, this pinion, in turn, engaging a gear 394 fast upon the eccentric 374. Extending across the under face of the disk 386 at one side of the axis is a slot 396, in which a carrier-block 398 may be adjusted by a screw 399 turning upon the disk and threaded through the block. A pin 400 depends from the block, and mounted to swing about this pin is a carrier-arm 402 for the knife K. Said knife is straight and is removably clamped by a set-screw 401 in rectilinear ways in a holder 403 upon the arm, with the cutting edge of the knife lying at the same angle as the surface 318 of the pattern P. The revolution of the pin 400 by the disk 386 superposed upon the orbital travel of the pin 380 causes the pin 400 to follow a path indicated by the dash-and-dot figure b in Fig. 18. This differs from the path a in being contracted at both sides along the minor axis, and thus more closely conforming to the contour of the pattern. Due to the location of the slot 396 at one side of the axis of the disk 386, this contraction is greater at one side of the path b than at the other, giving closer correspondence to the outline of a sole. The force applied to the knife from the pin 400 is, throughout its travel, very nearly tangential to the pattern, causing the cut in the stock to be made most effectively. When the range of sizes operated upon is considerable, the consequent change in the path which must be followed by the pin 400 to obtain the best results may be controlled by adjusting said pin along the slot in the disk 386 by the screw 399. In its revolution about the pattern, the arm 402 and its actuating elements may receive the support of and have the reaction to the cutting thrust of the knife resisted by a continuous track or contact-rail 404 carried horizontally, substantially parallel to the plane of the pattern, upon lugs 406 projecting from the inside of the housing 300. A bracket 408 rising from the eccentric-strap 378 has rotatable in it the horizontal stem of a yoke 410, upon the arms of which yoke turn rolls 412, 412 bearing upon opposite faces of the rail. On the under side of the eccentric-strap is a contact-plate 413 and against this bear projections 415 from the upper side of the arm 402. This transmits the thrust of the arm 402 through the strap to the rail 404, while permitting movement of the arm on the strap.

To draw the free end of the arm 402 toward the pattern P, and therefore to bring the knife into operating relation to said pattern, the arm has an extension 414 united by a link 416 to a tension-arm 418 arranged to oscillate about a stud 420 secured to the top of and depending through a casing 422 fixed against movement upon an arm forming a part of the eccentric-strap 378 (Figs. 10, 16 and 18). Turning upon the lower end of the stud is a disk 424, in which is an arcuate series of openings 426, any one of which may receive a pin 428 passing through the arm 418. Within the casing 422, with one extremity connected thereto, is a torsion-spring 430, the opposite end

of which engages an opening 432 in the disk. By shifting the pin 428 to one or another of the openings 426, the force exerted by the spring upon the arm 402 may be changed. For holding the arm 402 away from the pattern upon such occasions as when the knife K is to be changed, a latch 440 is shown as sliding upon the top of the arm 418 and movable into engagement with a projection 442 from the casing 422. Normally, the latch is drawn back as appears in Figs. 16, 17 and 18. But when the knife-arm is swung clear of the pattern, the latch may be pushed behind the projection, and the knife-arm held in this inactive position against the force of the spring 430.

When stock is undercut by the knife K, as shown in Figs. 15 and 20 to 26, inclusive, the point of said knife must normally lie above the lower face of the pattern P, against which the stock is raised and pressed by the clamping device Q, and means is provided for depressing the knife for its cutting travel after the engagement between the stock and pattern has been effected. Otherwise the knife, extending beneath the pattern in the cutting position, would initially enter the material of the sole itself, as the stock was raised by the device Q, and mutilate it. I may control the stock-engaging movement of the knife in the following manner: The knife-holder 403 is mounted upon the arm 402 by a vertical extension 444 having alined openings in horizontal lugs 446, 446 to receive a pin 448 fixed in the arm. Upon this pin the holder is free to both turn and move vertically, and is urged normally upward by a helical spring 450 interposed between the arm and the lower holder-lug 446, this acting to hold the point k of the knife above the under face of the pattern (Fig. 20). When there is no opposing force offered to the spring 430, it draws the holder against the pattern with a surface substantially flush with the inner face of the knife bearing upon the pattern-surface 318 in substantial vertical alignment with the axis of the pin 448. Freedom from contact of the knife with the pattern avoids nicking of the former and cutting of the latter. A component of the force of the spring 430 moves the knife down over said surface laterally of the pattern (Figs. 22 and 23), compressing the spring 450, this continuing until a pair of rolls 452, journaled upon the holder 403 with their axes inclined oppositely to the knife, contact with the pattern-surface 320 (Fig. 24). The knife is now in its operating position, the point k being sufficiently below the under face of the pattern to pass through the stock and somewhat into the belt 120, these having been elevated by the clamping device Q. The axes of the rolls lie at the opposite sides of the knife-edge and the line of contact of the holder with the pattern, and substantially equidistant from a vertical therethrough, tending to maintain said edge substantially normal to the pattern-edge throughout its travel. At the completion of the cutting operation and just before the cut stock is freed by the lowering of the clamping device, the knife is drawn from said stock by swinging the arm 402 outwardly to carry the holder away from the pattern and thus permit the spring 450 to elevate the holder until the point k of the knife is above the stock. For this purpose, there is fast upon the pin 400, clamped between the end of a surrounding bushing 454 and a nut 456 threaded upon the end of the pin, a pinion 458 (Figs. 15 and 30). Rotatable about the bushing 454, and separated from the pinion 458 by a washer 460, is a cam 462

having formed upon it a gear 464. The pinion 458, which is the driving element, is caused to turn the gear 464 by reduction-gearing 466 rotatable about a spindle 468 fixed vertically at the outer extremity of an extension of the arm 402. Each time the disk 386 rotates under the influence of the gearing 390, 394, it turns through the gearing 458, 466, 466 and 464 the cam 462, the gear-ratio being such that said cam is turned through 360° during the two revolutions of the knife-arm about the pattern. With the cam contacts a roll 470 rotatable upon a lever 472 fulcrumed upon the arm 402 and urged toward the cam by a spring 473. This lever is linked at 474 to a bell-crank lever 476 fulcrumed upon the arm. A roll 478 upon the outer extremity of the lever 476 co-operates with the vertical edge 316 of the pattern. The contour of the cam is such that, as for the clamping device Q raises the stock (Fig. 21), the roll 478 is forced by the connecting chain of elements against the surface 316 of the pattern, and thus the knife-arm is swung outwardly. Released from the downward force produced by the spring 430 acting through the knife-holder 403 upon the pattern-surface 318, said holder is elevated by the spring 450, raising the knife until its point is above the under face of the pattern (Figs. 25 and 26). The stock may therefore be raised against the pattern in preparation for the cutting operation (Fig. 21), without the area from which the sole is to be severed being mutilated by the entrance of the knife. This condition exists during a portion of a revolution of the knife-arm. Then the cam releases the roll 478, and the spring 430, urging the knife-holder against the surface 318, causes it to descend, compressing the spring 450. This continues until the holder-rolls 452 are seated upon the pattern-surface 320, at which time the knife is in its cutting relation below the pattern, where it is maintained until after somewhat more than a complete revolution of the arm 402, a sole thus being severed from the surrounding stock. Again the cam 462 acts as first described to withdraw the knife for the descent of the pressure device and cut sole and the advance of the stock for the succeeding operation. It should be observed that, in its withdrawal, the knife moves along the bevel which it has cut, not entering the stock outside this. As a result, the areas in the web from which the soles are to be formed may be closely spaced and there is no waste of cutting effect.

When forming outside-bevel or straight-edge soles, I preferably utilize the mechanism D arranged for overcutting as illustrated in Fig. 31 in which the straight knife N extends downwardly and outwardly from above a pattern p. This presents an advantage, in that the knife is making the cut in stock which lies beyond the peripheries of the pattern and pressure device, and less resistance is offered to this action than when the knife is operating in compressed stock, as in undercutting. Therefore, the outline of the pattern may be more accurately followed, the cut pieces being free from circumferential irregularities and without fins projecting from the upper and lower surfaces. Then too, the absence of outward pressure lessens the tendency of the pieces to adhere to the remainder of the web. It also permits a considerably simplified structure, as consideration of the following description will render obvious. In view of this, the overcutting arrangement is best used if stock-reversal is to be resorted to, instead of the change of cutting devices, as has been described. In

Fig. 31 appears the outer portion of the knife-carrying arm 402, which may be identical with that of Fig. 15. The arm 402 has a knife-holder 498 pivotally mounted upon its outer extremity by lugs 492, as in the undercutting arrangement. 5 No vertical movement of the holder is necessary, but, to avoid changing the arm 402, it may be used for the overcutting knife N as well as for the undercutting knife K and only the holder 498 substituted for the holder 493. This will 10 lead to an idle movement of the knife N away from the pattern p, which movement would not occur were a special arm employed for overcutting. In the latter case, the holder remains at all times seated in the angle of the pattern p. When 15 the stock R is forced against said pattern by the elevation of the pressure device, the point of the knife N enters the material outside the area which is to furnish the sole, and cuts its way in until the upper surface of the stock is in contact with 20 the under face of the pattern. With the elements thus positioned, the knife completes the cutting of the work to its true form by revolving through somewhat more than 360°. Then the pressure device and stock descend together, the knife again 25 cutting outside the sole-area until it is clear. At all times its cutting action, during approach and recession and other than that which effects the production of the sole, occurs in the scrap-material. During the cutting operation, the pattern p tends to retain the holder at all times against vertical displacement under the influence of both the cutting stresses and the weight of the parts, it having about its periphery lower and upper inclined surfaces 494 and 496, forming a 30 re-entrant or internal angle. Into this angle the lower, knife-block-portion of the holder 498 fits, having inwardly converging faces 500 and 502 respectively corresponding in inclination to the pattern-surfaces 494 and 496. The block is 35 shown as vertically divided between dovetailed ways 504, 504 (Fig. 34), and in these ways the knife N is clamped by a screw 503, which draws the portions of the block toward each other. Instead of rolls furnishing separated lines of 40 bearing for the holder-block to maintain the knife substantially normal to the curved edge of the pattern, said block has the bearing-face 502 furnished by two curved projections 510, 510 (Fig. 33), points of contact of these projections 45 with the pattern being equidistant from a vertical plane through the cutting edge of the knife. Such bearing-projections may be formed quite closely to each other, so there is little tendency for the knife to depart from its normal relation 50 to the pattern-edge when there are somewhat abrupt changes of curvature.

There is shown in Fig. 31, in connection with the just-described form of knife-mounting, a contact-rail 514, with bearing-rolls 516, 516 rotatable upon a yoke 518, the arrangement being similar to that of Fig. 15. Here, the rail is utilized to furnish a convenient manner of supplying electrical current for heating the knife. If the temperature of a knife employed to cut rubber is 55 raised, it is found that the cut is made more easily, and less frequent sharpening of the knife is necessary, the effect of the heat upon the rubber being to perform a part of the work of dividing it. In the present instance, the heating of 60 the knife is effected electrically, a heating unit 520 being secured vertically upon the holder 498. From the unit, conductors 522, 522 lead to brushes 524, 524 carried by holders 526 (Fig. 32) pivoted upon the yoke outside the respective rolls 516. 65 70 75 75

5 Springs 528 act upon the holders to force the brushes against opposite collector-rings 530, 531 mounted upon and insulated from the upper and under sides of the rail 514. A pair of conductors 532 supplies current to the collector-rings. By this arrangement, current may be delivered to the unit in all positions of the knife-arm. The unit 520 may be so chosen and mounted that there is such a continuous application of current as to 10 raise the temperature of the knife 506 to give the best cutting effect. Though this heating means has been illustrated only in connection with the knife of Fig. 31, it is equally applicable to the knife and its mounting shown in Fig. 15.

15 After the sole S has been severed from the web-material R, and the clamping device Q, carrying with it the sole and stock, lowered from the pattern P or p, the advance of the belt 120 occurs to move the area operated upon from the cutting 20 mechanism at D and to present another area for cutting. The web beyond the cutting mechanism is led beneath an idle guide-roll 534 (Fig. 11) and then up upon a belt-conveyor 536, which runs over a roll 538 journaled horizontally upon brackets projecting from the housing 390 and over a distant roll (not illustrated). The conveyor is 25 driven by sprocket-gearing 540 from the shaft 125 of the feeding mechanism. The cut soles, having been under heavy pressure between the pattern 30 and the somewhat rough surface of the belt 120, adhere to the latter. When the web of scrap-material which has not been thus compressed is guided upwardly by the roll 534, the soles leave it and are carried down by the belt 120 over the roll 35 123, the inclined edges yielding as the soles are drawn through the web-openings. At the forward side of said roll, the soles contact with a scraper 542 mounted across the frame 32 and having its upper edge resting against the belt. 40 They are thereby removed from said belt, falling upon a forwardly extending conveyor 544 operating over a roll 546 journaled horizontally upon the frame and over an outer roll (not illustrated). This conveyor 544 may be driven by sprocket-gearing 548 from the shaft of roll 538. From the 45 conveyor 544, the cut soles S may be removed for utilization, while the scrap is carried by the conveyor 536 to a point at which it may be collected for reworking.

50 Power for operating the feeding mechanism B, the embossing mechanism C, the cutting mechanism D and the separating and conveying mechanism E is applied to the shaft 224 from the driving mechanism F. This driving mechanism includes controlling means which allows the apparatus to be operated uninterruptedly to cut successive soles from the web without attention on the part of the operator, to perform a single operating cycle and thus cut one sole from the web, 55 to be inched or actuated gradually through a partial cycle or more to facilitate setting or adjustment, and to be instantly stopped during operation in any manner. Referring to Figs. 2, 10, 11, 12, 13 and 14 there is supported upon the lower 60 portion of the frame 32 an electric motor 552 with its shaft joined by belt-gearing 554 to a pulley 556 normally free to turn upon a shaft 558 journaled in the frame below and at right angles to the shaft 224, to which it is connected by 65 worm-gearing 560. The outer face of the pulley 556 furnishes one member of a friction-clutch I. The other member is shown as a disk 561 splined to move along the shaft 558, there being a spring 562 interposed between the disk and a collar 564 70 adjustable upon the outer extremity of the shaft, 75

which spring, unrestrained, causes the driving engagement of the clutch and consequent rotation of the shaft 224. A peripherally slotted hub of the disk 561 is engaged by the forked lower end of a three-armed lever 566 fulcrumed upon the 5 frame. An upwardly extending arm 568 of the lever may be engaged at 570 by a latch-bar 572 to hold the clutch I open against the action of the spring 562. The latch-bar is pivotally supported upon a lever 574 turning upon the frame and is provided with an adjustable contact-piece 576 for engagement with the clutch-lever 566. A roll 578 upon the lower end of the lever 574 has contacting with it a cam 580 secured upon the shaft 224. Under the influence of the high portion of 10 the cam, the latch-bar, by drawing its piece 576 against the lever-portion 570, acts to move the upper end of said lever to the right (Fig. 11), disengaging the clutch and stopping the apparatus. Because the cycle is terminated with the 15 high portion of the cam in contact with the roll 578, the latched relation, with the apparatus at rest, is maintained until the clutch-lever is freed by the operator. For this purpose and to cause continuous operation of the apparatus, a spindle 20 582 is arranged to turn transversely of the frame. At the operator's side of the apparatus, the spindle has fast upon it a crank 584 (Fig. 2) having a retaining pin 586, which may engage either 25 of two openings 588 in the frame. At the opposite extremity of the spindle from the crank-arm, there is fixed a collar 590, from which is an inward projection 592 entering a depression 593 30 (Fig. 14) somewhat extended circumferentially in the adjacent side of the hub of a lever 594 35 fulcrumed on the spindle 582. This lever may be turned anti-clockwise (Fig. 11) when the crank 584 is shifted from right to left. The movement forces a roll 596 upon the lever into contact with the under side of the latch-bar 572, raising it 40 against the tension of a spring 598 extending between the bar and the collar 590. The portion 576 of the bar is thereby lifted away from the clutch-lever portion 570, freeing the lever and permitting the spring 562 to cause the engagement 45 of the clutch I. Since, as long as the crank 584 is held at the left-hand opening 588 the latch-bar 572 is elevated, the clutch-releasing and latching element 576 cannot contact with the lever-portion 570, the cam 580 is ineffective, and 50 the apparatus continues to perform successive operating cycles.

To produce a single operating cycle only of the apparatus, there is arranged for contact with a short arm 600 of the lever 594 the upper 55 end of a rod 602 guided for vertical reciprocation in the frame and articulated at its lower extremity to an arm 604 projecting from a shaft 606 turning at the bottom of the frame 32 and having secured to it a treadle 608. Surrounding 60 the rod 602 and acting to depress it is a spring 610 interposed between a collar 612 adjustable along the rod and a horizontal arm 614 of the lever 566, through an opening in which arm the rod passes. The character of the spring 610, it being 65 weaker than the spring 562, is such that the rod 602 may be raised from its normal ineffective position without affecting the clutch I until said rod strikes the lever-arm 600. Although the crank-arm 584 is at this time secured in the 70 non-operating position, the lever 594 may be moved by this contact because of the extent of the depression 593, in which the less angularly extended projection 592 may remain at rest. The lever 594 therefore lifts the latch-bar 572 to carry 75

the contact-portion 576 away from the lever-portion 570. This unlatches the lever 566, allowing the spring 562 to establish engagement between the sections of the clutch I and starting the apparatus in operation. The lever-portion 570 now lies beneath the bar-portion 576. If, having done this, the operator releases the treadle, the apparatus will complete its cycle, during which the low section of the cam 580 will 5 so free the lever 574 that the spring 598 may shift the lever-roll 578 to the right (Fig. 11), the bar-portion 576 moving to the left of the lever-portion 570. As the cycle is completed, the high section of the cam, acting upon the roll 578, 10 swings the lever 574 clockwise, and the bar-portion 576, now contacting with the side of the lever-portion 570, turns the clutch-lever 566 clockwise. This opens the clutch and the apparatus stops. If at any time the operator wishes 15 to discontinue the operation of the apparatus, he fully depresses the treadle 608. Although this unlatches the clutch-lever 566, it also compresses the spring 618 to such an extent that it offers greater resistance than the spring 562. Consequently, pressure of the spring 618 against the 20 lever-arm 614 turns the lever 566 clockwise to disengage the clutch, regardless of how its operation was initiated or what point in the cycle has been reached. When the treadle is released, 25 provided the crank 584 is not set for continuous operation, the apparatus will complete any portion of a cycle which may have begun, and will then be stopped by the action of the cam 580. If the operator wishes to turn the apparatus over 30 gradually, this may be accomplished by causing the treadle to move between the position in which the clutch I is fully disengaged and that at which the spring 562 may establish driving engagement.

40 For the purpose of describing generally the operation of the apparatus, it will be assumed that it is desired to produce soles of a particular size of the type illustrated at S in Fig. 35 of the drawings, the periphery T having an inside bevel 45 for furnishing a rolled edge when applied to a shoe-bottom. The web R of rubber stock to be operated upon will be of a width permitting of the chosen length of sole to be cut economically and will have had one side embossed with a pattern, as by calender-rolls, over the areas from 50 which the forepart U and the heel-portion V of the soles are to be formed, the intermediate shank-area of the web being often left smooth or having a finer pattern. Upon this shank surface the trade-mark design X and size-number Y are to be impressed during the production of each sole. The pattern-side of the stock is preferably upmost as it travels through the apparatus, and the mechanism D with the undercutting 55 knife K will be employed. The flanges 114 are so adjusted upon the roll 112 associated with the feed-roll 110 of the mechanism B and the wall 117 located on the table 118 that they will contact with the edges of the web to correctly 60 guide this to the embossing mechanism C and the cutting mechanism D. Their positions will correspond to the width of the web and therefore to the size of the pattern. The length of the feeding steps of the mechanism B to correspond 65 to the size of sole being made is regulated by rotation of the hand-wheel 190 (Fig. 2). The embossing mechanism is correspondingly spaced from the cutting mechanism longitudinally of the line of feed by turning the hand-crank 270; and the position of the holders 248,

248 transversely of the web and line of feed to symmetrically locate the designs X, Y upon the shank of the sole longitudinally of its axis is provided for by adjustment of the hand-wheel 236 (Fig. 19). Since the previously embossed pattern upon the stock is at its upper side, the trade-mark and size-dies will be inserted in the upper holder 248 and a smooth platen in the lower holder. By adjustment of the hand-wheels 252, 252, the dies and platen are caused to so engage the stock at the line of feed as to give a perfect impression. A pattern P of the appropriate size and contour is secured upon the supporting spindle 302. At the unreeling mechanism A, a supply-reel 40 (Fig. 1) is mounted, this carrying the stock R coiled with a slatted separator L and with an auxiliary web-separator I, the side of the stock bearing the pattern being outward. These separators are attached to their respective receiving reels 60 and 78, and the loose end 20 of the web of stock led between the guide-roll 112 and feed-roll 110 and across the table 118 to the embossing mechanism C, where the operator depresses the gage-pin 290 (Fig. 19) and positions the forward extremity of the stock by contact with the rear side of the pin. Enough stock has been unreeled at this time to furnish the controlling loop r between the unreeling mechanism and the feed-roll 110. Partially depressing the treadle 608 (Fig. 11), the operator 25 trips the clutch I to cause the operation of the apparatus for a single cycle under the influence of the driving mechanism F. At the beginning of this cycle, the feed mechanism advances the stock a half of a feeding step, this presenting the 30 terminal area to the dies and platen of the embossing mechanism C for the production of the first impression of the trade-mark X and size- 35 designation Y. There are at this time, and for certain succeeding cycles, idle operations of the 40 cutting apparatus D. Other similar depressions of the treadle result in the embossing of succeeding sole-areas and the advance of the end of the web beneath the retaining rolls 350 upon the feed-belt 120 into such a position between the 45 pattern P and the pressure device Q that the portion first operated upon is located for cutting. In the feed of the stock, its unreeling is at all times governed by the length of the loop r, it acting through the controlling lever 96 and the 50 clutch 54 to apply power for uncoiling the stock from the supply-reel 40 and coiling the separators upon the receiving reels 60 and 78. Under no conditions does the feeding mechanism impose any deforming force upon the stock, and a 55 sufficient amount of said stock from which to feed is continually maintained unreeled in the loop r without adjustment, regardless of the frequency of action of the operating means and of the size of the soles being cut, and therefore 60 of the length of the feeding steps. The feeding and embossing mechanisms having been correctly set, as already indicated, the proper registration of the impression upon the shank-portion 65 of each sole will be assured, there being no opportunity for displacement of the impressed area between the embossing and cutting operations, because said area remains a part of the continuous web. If I chose to cut the soles before embossing rather than after, they would 70 still be held against displacement by the engagement of their peripheries with the edges of the openings in the web from which they have been severed. After the operator has inspected the first sole cut and found it satisfactory, he may 75

shift the hand-crank 584 to cause the driving mechanism F to automatically effect a series of embossing and cutting operations continuously until the crank is restored to its inactive position or the treadle 608 fully depressed, the latter especially providing for an emergency-stop during either the single-cycle testing or the continuous-production operation.

At the cutting mechanism, the carrier-arm 402 (Figs. 15 to 18) is constantly revolving about the pattern while the apparatus is in operation, its pivotal point 400 being caused by the combined action of the eccentric 374, the crank-arm 376 and the disk 386 to follow a path approximating the contour of the pattern; see the curve b, Fig. 18. Therefore, the cutting force applied to the knife K mounted upon the arm 402 and held in co-operation with the pattern by the spring 430 is in such a direction, generally tangential to the curve of the pattern, that its cut will be made smoothly and with a minimum resistance. During a portion of each double revolution of the carrier-arm, the point k of the knife, which is inclined at the angle of the lower inclined peripheral surface 318 of the pattern, is held above the lower face of said pattern (Fig. 20) by the spring 450, which urges the carrier 444 for the knife-holder 403 upwardly upon the carrier-arm. The spring 450 is permitted to act at this time by the cam 462, which moves the arm and holder away from the pattern and the retaining effect of the surface 318. The pressure device Q is elevated to lift the feed-belt 120 and the stock thereon (Fig. 21) and clamp it against the lower face of the pattern (Fig. 22). Now the cam 462 frees the arm, and the spring 430 draws the holder into contact with the periphery of the pattern. The resulting pressure of the inclined surface of the holder adjacent to the knife upon the pattern-surface 318 causes the spring 450 to yield and the holder and knife to ride down said pattern-surface until the holder is stopped by the engagement of the rolls 452 with the upper inclined surface 320. The knife is now traveling through the stock under the guidance of the pattern, said knife slightly penetrating the belt 120 (Fig. 23) to insure complete severance of the sole. This continues through somewhat more than a revolution of the knife about the pattern, at which time the sole has been fully cut (Fig. 24). Thereupon the cam 462 comes into action and the arm 402 is again swung outwardly, permitting the spring 450 to become effective to elevate the point of the knife above the lower face of the pattern (Fig. 25). Then the pressure device Q falls carrying the belt 120 and the stock with it (Fig. 26), the cutting operation being completed without the inwardly projecting knife entering and mutilating the sole-area. If there is to be cut an outside-bevel sole, to give a straight edge, instead of the inside bevel as just described, the holder 444 may be removed from the cutting mechanism and the holder 492 with its knife N (Fig. 31) substituted, while the pattern p takes the place of the pattern P. In both forms of pattern, the inclined surfaces co-operate with the knife-holder to resist vertical displacement, and a contact-rail such as 404 or 514 may or may not be provided, as is considered best. But if the knife is to be heated electrically by the unit 520 to facilitate its cutting action, the rail forms a convenient means for supplying current. The previous description, both for undercutting and overcutting, applies either to the formation of a right sole or a left sole. For the production, in

each instance, of the other or the opposite sole the pattern is reversed, the manner of attaching it to its supporting spindle 302 facilitating this and rendering the mounting secure. In this reversal, the functions of the surfaces 318 and 320 of the pattern P having the external angle and the surfaces 494 and 496 of the pattern p with the re-entrant angle are interchanged. Because of the separation of the embossing and cutting mechanisms, the dies of the former are not limited in size by the patterns and the changing of said patterns is facilitated.

The embossed cut soles pass from the mechanism D to the mechanism E, where the scraper 542 removes from the belt 120 the soles adhering to it because of the pressure exerted upon them between the pattern P or p and the device Q. The scrap, still in web-form, with the soles separated from it, is directed upwardly and carried from the apparatus by the conveyor 536.

Having described my invention, what I claim as new and desire to secure by Letters Patent of the United States is:

1. In an apparatus for cutting rubber stock, a rotatable reel for a web of stock, a pattern, a cutting device, means for moving the device about the pattern in a cutting period and in an inactive period, means for feeding the stock step by step in co-operation with the pattern during the inactive period of the cutting device, a rotatable reel for the stock, and means operating independently of the feeding means for rotating the reel and supplying the stock to said feeding means.

2. In an apparatus for cutting rubber stock, a rotatable reel for a web of stock, a pattern, a cutting device, means for moving the device about the pattern in a cutting period and in an inactive period, means for feeding the stock step by step in co-operation with the pattern during the inactive period of the cutting device, a rotatable reel for the stock, and means governed by the stock for rotating the reel to supply said stock to the feeding means.

3. In an apparatus for producing beveled soles from a strip of rubber stock, means for advancing the strip, means for successively cutting soles with beveled edges from the strip, and embossing mechanism having a holder mounted at each side of the path of advance of the strip and a die for embossing a sole-area of the strip, said die being arranged to be mounted interchangeably in either holder.

4. In an apparatus for producing soles from a strip of rubber stock, means for cutting the soles from the strip, and embossing mechanism having a die for embossing a sole-area of the strip, a platen having a smooth surface for co-operation with the die and means arranged to mount the die and platen interchangeably at opposite sides of the strip.

5. In an apparatus for producing soles from a strip of rubber stock, means for cutting the soles from the strip, and embossing mechanism spaced along the strip from the cutting means, said embossing mechanism having members movable toward and from opposite sides of the strip, a holder carried by each member and means arranged to mount a die in either holder.

6. In an apparatus for producing soles from rubber stock, cutting mechanism having a traveling cutter, embossing mechanism having opposite relatively movable members, means for moving the stock between the members to receive their embossing action and thereafter advanc-

- ing the embossed stock into co-operation with the cutting mechanism, and means for causing the travel of the cutter about the area of the stock which has been acted upon by the embossing mechanism.
7. In an apparatus for producing soles from rubber stock, cutting mechanism, embossing mechanism having opposite relatively movable members and a die and platen arranged to be interchangeably mounted upon the members, and a feed-roll and feed-belt arranged to move the stock between the embossing members and into co-operation with the cutting mechanism.
8. In an apparatus for producing soles from a strip of rubber stock, mechanism for cutting soles with their maximum dimension lying transversely of the strip, embossing mechanism, feeding means movable step by step to present the strip successively to the two mechanisms, means arranged to vary the length of the steps to correspond to the width of the soles being cut, and means arranged to change the space between the cutting mechanism and the embossing mechanism longitudinally of the feeding means to correspond to the length of the feeding steps and the width of the soles.
9. In an apparatus for producing soles from rubber stock, a frame, cutting mechanism operable thereon, a carrier movable upon the frame toward and from the cutting mechanism, embossing mechanism movable upon the carrier into and out of contact with opposite sides of the stock, and means for feeding the stock from one mechanism to the other.
10. In an apparatus for producing soles from rubber stock, a frame, cutting mechanism operable thereon, a carrier movable upon the frame toward and from the cutting mechanism, embossing mechanism mounted upon the carrier, means for feeding the stock step by step from one mechanism to the other, means for varying the length of the feeding steps to correspond to different sole-sizes, and index means associated with the carrier and graduated in sole-sizes.
11. In an apparatus for producing soles from rubber stock, means for feeding the stock, mechanism arranged to cut soles of different sizes from the stock, mechanism having opposite members for embossing the stock, said mechanisms being spaced from each other along the line of feed, and means arranged to vary simultaneously the position of both embossing members transversely of the line of feed.
12. In an apparatus for operating upon rubber stock, means for feeding the stock, a support arranged to interchangeably receive patterns of different sizes, cutting mechanism co-operating with the supported pattern, mechanism having a die for embossing the stock, said mechanisms being spaced from each other along the line of feed, and means for varying the position of the die to correspond to the size of the pattern.
13. In an apparatus for producing soles from rubber stock, means for feeding the stock, mechanism arranged to cut soles of different sizes from the stock, embossing mechanism having holders supported upon opposite sides of the stock, either of said holders being arranged to receive an embossing die, and means for simultaneously varying the positions of the holders.
14. In an apparatus for producing soles from rubber stock, means for feeding the stock, mechanism arranged to cut soles of different sizes from the stock, embossing mechanism having holders supported upon opposite sides of the stock, either
- 5 of said holders being arranged to receive an embossing die, and means for varying the position of the holders transversely of the line of feed.
15. In an apparatus for producing soles from rubber stock, means for feeding the stock, mechanism arranged to cut soles of different sizes from the stock, actuating members movable toward and from opposite sides of the stock, impression means movable upon the actuating members, and connections between the impression means arranged to move them simultaneously.
16. In an apparatus for producing soles from rubber stock, means for feeding the stock, mechanism arranged to cut soles of different sizes from the stock, actuating members movable toward and from opposite sides of the stock, holders movable upon the actuating members, a die and platen interchangeably mounted in the holders, and connections between the holders arranged to move them simultaneously.
17. In an apparatus for producing soles from a strip of rubber stock with their maximum dimension extending transversely of the strip, feeding means for advancing the strip of stock step by step, means arranged to vary the length of the steps to correspond to soles of different widths, cutting mechanism and embossing mechanism to which the feeding means delivers the stock, said embossing mechanism having a die, means arranged to vary the position of the embossing mechanism toward and from the cutting mechanism in accordance with the width of the soles, and means arranged to vary the position of the die upon the embossing mechanism to locate the impression longitudinally of the shank-portion of the soles.
18. In an apparatus for producing soles from rubber stock, a frame, cutting mechanism operable thereon, a carrier movable upon the frame toward and from the cutting mechanism, embossing mechanism comprising opposite members movable upon the carrier and including a die, means for adjusting the position of the die independently of the movement of the carrier, and means for feeding the stock from one mechanism to the other.
19. In an apparatus for producing soles from rubber stock, a frame, cutting mechanism operable thereon, a carrier movable upon the frame toward and from the cutting mechanism, actuating members movable upon the carrier toward and from the opposite sides of the stock, impression means movable upon the members, and connections between the impression means arranged to move them simultaneously.
20. In an apparatus for producing soles from rubber stock, a frame, cutting mechanism operable thereon, a carrier movable upon the frame toward and from the cutting mechanism, actuating members movable upon the carrier toward and from the opposite sides of the stock, holders movable upon the members, a die and a platen interchangeably mounted in the holders, and connections between the holders arranged to move them simultaneously upon the actuating members.
21. In an apparatus for producing soles from rubber stock, mechanism for cutting soles of different sizes, embossing mechanism, means for feeding the rubber stock to the mechanisms from a coiled web, guiding means for engagement with the opposite edges of the stock, means arranged to adjust the guiding means transversely of the line of feed to correspond to different sizes of soles, and means for varying the position of the 70

embossing mechanism in accordance with the size of the sole to be cut.

22. In an apparatus for producing soles from a web of rubber stock, mechanism for cutting soles of different sizes, embossing mechanism having a die, a belt for feeding the web and with which the cutting mechanism co-operates, a guide-roll extending transversely of the web and having guide-flanges for engagement with the web and adjustable longitudinally of the axis of the roll, and means arranged to vary the position of the die transversely of the web.

23. In an apparatus for operating upon a web of rubber stock, embossing mechanism and cutting mechanism acting successively upon the web, means for advancing the stock through the embossing and cutting mechanisms, said cutting mechanism having members contacting with one face of each cut piece and with the advancing means at the opposite face and said members being movable relatively to force said cut piece and advancing means into engagement, and means for separating the embossed and cut pieces and the scrap from the advancing means.

24. In an apparatus for producing soles from rubber stock, feeding mechanism movable to advance the stock intermittently, cutting mechanism operating upon the stock during the intermittencies of feed, driving mechanism for the feeding and cutting mechanisms, and controlling mechanism for the driving mechanism, said controlling mechanism having a member movable by the operator to produce continuous operation of the apparatus for cutting soles successively from the stock and a second member movable by the operator to cause a single operating cycle with the cutting of one sole.

25. In an apparatus for producing soles from rubber stock, feeding mechanism movable to advance the stock intermittently, cutting mechanism operating upon the stock during the intermittencies of feed, driving mechanism for the feeding and cutting mechanisms, and controlling mechanism for the driving mechanism, said controlling mechanism having a member movable by the operator to produce continuous operation of the apparatus for cutting soles successively from the stock and a second member movable by the operator to cause a single operating cycle with the cutting of one sole, one of said members being arranged in its movement to disconnect the driving mechanism from the feeding and cutting mechanism.

26. In an apparatus for producing soles from rubber stock, feeding mechanism movable to advance the stock intermittently, cutting mechanism operating upon the stock during the intermittencies of feed, driving mechanism for the feeding and cutting mechanisms, and controlling mechanism for the driving mechanism, said controlling mechanism having a member movable by the operator to produce continuous operation of the apparatus for cutting soles successively from the stock and a second member movable by the operator to cause a single operating cycle with the cutting of one sole, the latter member being arranged upon its further movement to disconnect the driving mechanism from the feeding and cutting mechanisms.

27. In an apparatus for producing soles from rubber stock, feeding mechanism movable to advance the stock intermittently, cutting mechanism operating upon the stock during the intermittencies of feed, driving mechanism for the feeding and cutting mechanisms, and controlling

mechanism for the driving mechanism, said controlling mechanism having a crank movable to produce continuous operation of the apparatus, means for locking the crank in inactive and active positions and a treadle movable to cause a single operating cycle of said apparatus.

28. In an apparatus for producing soles from rubber stock, feeding mechanism movable to advance the stock intermittently, cutting mechanism operating upon the stock during the intermittencies of feed, driving mechanism for the feeding and cutting mechanisms, and controlling mechanism for the driving mechanism, said controlling mechanism having a crank movable to produce continuous operation of the apparatus, means for locking the crank in inactive and active positions and a treadle depressible through a portion of its travel to cause a single operating cycle of said apparatus, the treadle being further depressible to stop the apparatus.

29. In an apparatus for cutting a web of rubber stock, a pattern, a knife associated with the pattern, means for feeding the web step by step into co-operation with the pattern and knife, a support for the web, and means for delivering the web from the support to the feeding means.

30. In an apparatus for cutting a web of rubber stock, a knife, means for moving the knife along an elongated closed path, means for intermittently advancing the web to receive the action of the knife, a supply-reel for the web, and means for rotating the reel to deliver the web to the advancing means.

31. In an apparatus for operating upon rubber stock, operating mechanism, a stock-feeding belt co-operating with the operating mechanism, a reel for a web of stock, means for delivering stock from the reel, and a feed-roll engaging the stock to advance it from the reel toward the belt.

32. In an apparatus for operating upon rubber stock, a frame, a table supported upon the frame and with which the stock contacts, mechanism for operating on the stock resting upon the table, a feed-roll rotatable at the outer side of the table and delivering stock thereto, a feed-belt receiving the stock from the inner side of the table, and mechanism for operating on the stock upon the belt.

33. In an apparatus for cutting rubber stock, a frame, a table supported upon the frame and with which the stock contacts, embossing mechanism operating on the stock resting upon the table, a feed-roll rotatable at the outer side of the table and delivering stock thereto, a feed-belt receiving the stock from the inner side of the table, and cutting mechanism operating upon the stock carried by the belt.

34. In an apparatus for cutting soles from rubber stock, a traveling cutting device, a support arranged to hold interchangeably patterns of different sizes for co-operation with the cutting device, feeding means for advancing the stock to receive the action of the cutting device, means engaging the opposite edges of the stock and movable in engagement therewith for guiding said stock during its feed, and means arranged to vary the position of the guiding means at each edge of the stock to correspond to the length of the pattern.

35. In an apparatus for cutting soles from rubber stock, a traveling cutting device, a support arranged to hold interchangeably patterns of different sizes for cooperation with the cutting device, means for supplying stock, a rotatable roll for advancing the stock from the supplying

- means to receive the action of the cutting device, means for guiding the stock during its feed and increasing the arc of engagement with the roll, and means arranged to adjustably position the guiding means relatively to the feeding means.
36. In an apparatus for cutting rubber stock, a pattern, a cutting device, means for moving the device about the pattern to make the cut, an endless belt movable with reference to the pattern and cutting device to present the rubber stock thereto, said belt being arranged to be penetrated by the cutting device during the cutting of the stock, and means for advancing the belt intermittently.
37. In an apparatus for cutting rubber stock, a pattern, a cutting device, means for moving the device about the pattern to make the cut, an endless belt movable with reference to the pattern and cutting device to present the rubber stock thereto, said belt being arranged to be penetrated by the cutting device during the cutting of the stock, means for advancing the belt intermittently, and means for pressing the stock and belt toward the pattern during the cutting operation.
38. In an apparatus for cutting rubber stock, cutting mechanism, two guide-rolls having their axes substantially in a horizontal plane, a belt operating over the rolls and arranged to support between the rolls the work for the cutting operation, said belt following a generally triangular path, means for driving one of the rolls, and a guide and tension-roll engaging inner face of the belt below the two guide-rolls at the lower apex of the triangle.
39. In an apparatus for cutting rubber stock, cutting mechanism, a feed-belt co-operating with the cutting mechanism and arranged to support stock during the cutting operation, a tension member extending transversely in engagement with the belt, and a spring individual to each end of the tension member to urge it against the belt.
40. In an apparatus for cutting rubber stock, cutting mechanism, a feed-belt co-operating with the cutting mechanism, a roll engaging the belt and having movable bearings, a shaft having independently movable sections respectively connected to the bearings, a torsion-spring acting upon each section, and connections between the sections compelling them to move together while permitting limited independent movement.
41. In an apparatus for cutting rubber stock, cutting mechanism, a feed-belt co-operating with the cutting mechanism, a roll engaging the belt and having movable bearings, a shaft having independently movable sections respectively connected to the bearings, a torsion-spring acting upon each section, connections between the sections, and means arranged to shift the connections of the sections to vary the force of the springs.
42. In an apparatus for cutting rubber stock, cutting mechanism, a feed-belt co-operating with the cutting mechanism, a roll engaging the belt and having movable bearings, a shaft having independently movable sections respectively connected to the bearings, a torsion-spring acting upon each section, means arranged to turn the shaft and move the roll away from the belt, and a latch for the roll.
43. In an apparatus for cutting soles from rubber stock, cutting mechanism, a conveyor co-operating therewith, a driving roll over which the conveyor operates, an actuating arm for the roll, an oscillatory lever, means for oscillating the lever, a link connecting the actuating arm to an arm of the lever, one of said arms being curved about a center lying substantially at the pivotal connection between the link and the other arm, and means arranged to move the link-connection 5 along the curved arm.
44. In an apparatus for cutting soles from rubber stock, cutting mechanism, a conveyor co-operating therewith, a driving roll over which the conveyor operates, an actuating arm for the roll, an oscillatory lever, means for oscillating the lever, a link connecting the actuating arm to an arm of the lever, one of said arms being curved about a center lying substantially at the pivotal connection between the link and the other arm, a 10 screw rotatable upon the curved arm, a block movable longitudinally of said arm, and a nut engaged by the screw and connected to the block to move transversely of the arm.
45. In an apparatus for operating upon rubber stock, means for advancing a web of the stock for the operations upon it, impression members situated at opposite sides of the path of the advancing web, and means for moving both members positively oppositely into engagement with the web 15 to emboss the rubber to a definite depth.
46. In an apparatus for operating upon rubber stock, means for advancing a web of the stock for the operations upon it, levers fulcrumed at one side of the path of the advancing web and 20 extending above and below said path, impression members mounted upon the levers for engagement with opposite sides of the stock, and means for oscillating both levers through constant angles.
47. In an apparatus for operating upon rubber stock, means for feeding a web of stock for the operations upon it, impression members, means for mounting said impression members interchangeably at opposite sides of the path of the advancing web, and means for moving the members oppositely into engagement with the web at 25 the line of feed, with a constant depth of embossing impression in the rubber.
48. In an apparatus for operating upon rubber stock, means for advancing a web of the stock for the operations upon it, levers fulcrumed at one side of the path of the advancing web and extending above and below said path, a holder carried by each lever, and a die and a platen interchangeably mounted in the holders, the die entering 30 the rubber at either side of the web with a constant depth of embossing impression.
49. In an apparatus for operating upon rubber stock, means for advancing a web of the stock for the operations upon it, impression members situated at opposite sides of the path of the advancing web, means arranged to move the members transversely of said path and to maintain them in their adjusted position, and means for moving the members oppositely into engagement 35 with the web in the transverse relation in which they are thus fixed.
50. In an apparatus for operating upon rubber stock, means for advancing a web of the stock for the operations upon it, impression members situated at opposite sides of the path of the advancing web, means arranged to move one member transversely of said path, connections between the members arranged to transmit such transverse movement from the member moved to the other member, and means for moving the members oppositely into engagement with the web.
51. In an apparatus for operating upon rubber stock, means for advancing the stock for the operations upon it, levers fulcrumed at one side of the 40

the path of the advancing stock and extending above and below said path, a carrier movable upon each lever, connections between the carriers to move them simultaneously, an actuating member for the connections arranged upon one of the carriers, an impression member mounted upon each carrier, and means for oscillating the levers.

52. In an apparatus for operating upon rubber stock, means for advancing the stock for the operations upon it, levers fulcrumed at one side of the path of the advancing stock and extending above and below said path, a carrier movable upon each lever, an impression member mounted upon each carrier, a shaft rotatable in each lever and having threaded engagement with the carrier thereon, operating connections between the shafts, a hand-wheel fixed upon one of the shafts, and means for oscillating the levers.

53. In an apparatus for operating upon rubber stock, means for advancing a web of the stock for the operations upon it, impression members situated at opposite sides of the path of the advancing web, means arranged to adjust the members toward and from said stock, and means for moving the members oppositely into engagement with the stock at the line of feed with a constant depth of embossing impression in the rubber for each adjustment.

54. In an apparatus for operating upon rubber stock, means for advancing the stock for the operations upon it, levers fulcrumed at one side of the path of the advancing stock and extending above and below said path, impression members mounted upon the levers for engagement with opposite sides of the stock, means for moving each impression member upon its lever toward and from the companion member, and means for oscillating the levers.

55. In an apparatus for operating upon rubber stock, means for advancing the stock for the operations upon it, levers fulcrumed at one side of the path of the advancing stock and extending above and below said path, a holder movable upon each lever toward and from the companion lever, a screw rotatable upon each lever and having threaded engagement with the corresponding holder, impression members mounted upon the holders, and means for oscillating the levers.

56. In an apparatus for operating upon rubber stock, means for advancing the stock for the operations upon it, impression members situated at opposite sides of the path of the advancing stock, means arranged to move the members transversely of said path, means for adjusting the members toward and from the stock, and means for moving the members oppositely into engagement with the stock.

57. In an apparatus for operating upon rubber stock, means for advancing the stock for the operations upon it, levers fulcrumed at one side of the path of the advancing stock and extending above and below said path, a carrier movable upon each lever, a holder movable in each carrier, an impression member mounted upon each holder, and means for oscillating the levers.

58. In an apparatus for operating upon rubber stock, means for advancing the stock for the operations upon it, levers fulcrumed at one side of the path of the advancing stock and extending above and below said path, a carrier movable upon each lever, connections arranged to move the carriers simultaneously, a holder movable in each carrier, an impression member mounted upon each holder, means arranged to adjust each

holder toward and from the stock, and means for oscillating the levers.

59. In an apparatus for operating upon rubber stock, means for advancing the stock for the operations upon it, a carriage movable longitudinally of the path of the advancing stock, means arranged to thus move the carriage and retain it in adjusted position, impression members movable upon the carriage for operating upon opposite sides of the stock, and means for moving the members oppositely into engagement with the stock.

60. In an apparatus for operating upon rubber stock, means for advancing the stock for the operations upon it, a carriage movable longitudinally of the path of the advancing stock, impression members movable upon the carriage for operating upon opposite sides of the stock, a shaft rotatable substantially parallel to the path of the stock, and members rotatable by the shaft for actuating the impression members and being movable along the shaft in the travel of the carriage.

61. In an apparatus for operating upon rubber stock, means for advancing the stock for the operations upon it, a carriage movable longitudinally of the path of the advancing stock, operator-controlled means for moving the carriage, index means movable by said operator-controlled means, impression members movable upon the carriage for operating upon opposite sides of the stock, and means for moving the members oppositely into engagement with the stock.

62. In an apparatus for operating upon rubber stock, a frame, means for feeding work along the frame for the operations upon it, a carriage movable upon the frame parallel to the direction of feed, levers fulcrumed upon the carriage and extending upon opposite sides of the stock, impression members mounted upon levers for engagement with opposite sides of the stock, means for oscillating the levers, a screw rotatable upon the frame and having threaded engagement with the carriage, and operator-controlled means for rotating the screw.

63. In an apparatus for operating upon rubber stock, a frame, means for feeding work along the frame for the operations upon it, a carriage movable upon the frame parallel to the direction of feed, levers fulcrumed upon the carriage and extending upon opposite sides of the stock, impression members mounted upon the levers for engagement with opposite sides of the stock, means for oscillating the levers, a screw rotatable upon the frame and having threaded engagement with the carriage, and a shaft journaled transversely of the frame for rotation by the operator and connected to the screw.

64. In an apparatus for operating upon rubber stock, a frame, means for feeding work along the frame for the operations upon it, a carriage movable upon the frame parallel to the direction of feed, levers fulcrumed upon the carriage and extending upon opposite sides of the stock, impression members mounted upon the levers for engagement with opposite sides of the stock, means for oscillating the levers, a screw rotatable upon the frame and having threaded engagement with the carriage, a member controllable by the operator and connected to the screw, and an index-disk geared to the operator-controlled member.

65. In an apparatus for operating upon rubber stock, means for advancing the stock for the operations upon it, a carriage movable longitudinally of the path of the advancing stock, impression members movable upon the carriage for operating upon opposite sides of the stock, a shaft rotatable substantially parallel to the path of the stock, and members rotatable by the shaft for actuating the impression members and being movable along the shaft in the travel of the carriage.

- 5 dinally of the path of the advancing stock, means for securing the carriage against movement in its adjusted position, impression members movable upon the carriage for operating upon opposite sides of the stock and being arranged for movement transversely of said path, and means for moving the members oppositely into engagement with the stock.
- 10 66. In an apparatus for operating upon rubber stock, means for advancing the stock for the operations upon it, a carriage movable longitudinally of the path of the advancing stock, impression members movable upon the carriage for operating upon opposite sides of the stock and being arranged for adjustment toward and from the stock, and means for moving the members oppositely into engagement with the stock.
- 15 67. In an apparatus for operating upon rubber stock, means for advancing the stock for the operations upon it, a carriage movable longitudinally of the path of the advancing stock, impression members movable upon the carriage for operating upon opposite sides of the stock and being arranged for adjustment transversely of the path of the stock and toward and from said stock, and means for moving the members oppositely into engagement with the stock.
- 20 68. In an apparatus for operating upon rubber stock, means for advancing a web of the stock for the operations upon it, a carriage movable longitudinally of the path of the advancing web, levers fulcrumed upon the carriage and extending above and below the web, a carrier movable upon each lever, an impression member mounted upon each carrier, and means for oscillating the levers.
- 25 69. In an apparatus for operating upon rubber stock, means for advancing the stock for the operations upon it, a carriage movable longitudinally of the path of the advancing stock, levers fulcrumed upon the carriage and extending above and below the stock, a carrier movable upon each lever, a holder movable upon each carrier toward and from the companion carrier, an impression member mounted in each holder, and means for oscillating the levers.
- 30 70. In an apparatus for operating upon a web of rubber stock, operating mechanism having an element movable toward and from the web, means for feeding the web to the operating mechanism, and a gage mounted upon the movable element of the operating mechanism for receiving contact of the forward end of the web.
- 35 71. In an apparatus for operating upon rubber stock, operating mechanism having an element movable toward and from the stock, means for feeding the stock to the operating mechanism, and a gage yieldably mounted upon the movable element of the operating mechanism and arranged for movement by the operator into the path of the stock.
- 40 72. In an apparatus for operating upon rubber stock, operating mechanism having an element movable toward and from the stock and being adjustable with respect to said stock, means for feeding the stock to the operating mechanism, and a gage mounted upon the movable element of the operating mechanism for adjustment therewith.
- 45 73. In an apparatus for operating upon rubber stock, a lever fulcrumed for movement toward and from the stock, an impression member carried by the lever, means for feeding the stock to the impression member, and a gage member co-
- 50 operating with the impression member upon the lever.
- 55 74. In an apparatus for operating upon rubber stock, a lever fulcrumed for movement toward and from the stock, a carrier-block movable upon the lever, an impression member fixed in the carrier-block, means for feeding the stock to the impression member, and a gage-pin mounted upon the carrier-block adjacent to the impression member.
- 60 75. In an apparatus for operating upon rubber stock, a lever fulcrumed for movement toward and from the stock, a carrier-block movable upon the lever, an impression member fixed in the carrier-block, means for feeding the stock to the impression member, a gage-pin movable upon the carrier-block to opposite sides of the impression-surface of the member, and a spring normally holding the gage-pin out of the path of the stock.
- 65 76. In an apparatus for operating upon rubber stock, an impression member movable toward and from the stock during an operating cycle, means for feeding the stock step by step to the impression member, said feeding means being organized to stop at a half-step upon the termination of a cycle, and a gage movable with the impression member for engagement with the stock and having its rearward edge opposite the center of said member.
- 70 77. In an apparatus for cutting rubber stock, a cutting device, a pattern with which the cutting device co-operates, said pattern having an opening extending between its opposite faces and an inclined surface adjacent to the opening, a support for the pattern provided with a projection fixed against movement upon it and arranged to receive the pattern-opening, said projection having an inclined surface arranged for engagement by the inclined surface of the pattern by movement of said pattern upon the support, and means for maintaining the engagement of the inclined surfaces.
- 75 78. In an apparatus for cutting rubber stock, a cutting device, a pattern with which the cutting device co-operates, said pattern having spaced openings and an inclined surface adjacent to each opening, a support for the pattern provided with projections arranged to receive the pattern-openings, said projections having inclined surfaces arranged for engagement by the inclined surfaces of the pattern, and a latch member movable upon the support and engaging the pattern between its openings.
- 80 79. In an apparatus for cutting rubber stock, a cutting device, a reversible pattern with which the cutting device co-operates, a support having a surface for engagement by either face of the pattern, said support and pattern being respectively provided with means fixed against movement thereon and arranged to draw either of the faces of the pattern and the support together, and means movable upon the support for separably maintaining such engagement.
- 85 80. In an apparatus for cutting rubber stock, a cutting device, a reversible pattern with which the cutting device co-operates, said pattern having an opening between its opposite faces and inclined surfaces converging inwardly at the opening, a support for the pattern provided with a projection arranged to receive the pattern-opening and having an inclined surface for engagement with either inclined surface of the pattern, and means for separably maintaining such engagement.
- 90 81. In an apparatus for cutting rubber stock,

- 5 a cutting device, a reversible pattern with which the cutting device co-operates, said pattern having spaced openings between its opposite faces and inclined surfaces converging inwardly at each opening, a support for the pattern provided with a projection arranged to receive each pattern-opening and having an inclined surface for engagement by either inclined surface of a pattern-opening, and a spring-actuated latch-pin 10 movable upon the support and engaging the pattern between its openings.
- 15 82. A sole-cutting pattern provided with peripheral guide-surfaces oppositely inclined, said pattern being arranged for reversal to permit the cutting of either right or left soles.
- 20 83. A sole-cutting pattern provided with peripheral guide-surfaces oppositely inclined and forming with each other a salient angle, said pattern being arranged for reversal to permit the cutting of either right or left soles.
- 25 84. In a sole-cutting apparatus, cutting mechanism, and a sole-pattern with which the cutting mechanism co-operates, said pattern having oppositely inclined peripheral surfaces to receive contact of the cutting mechanism and being arranged for reversal to permit the cutting of either right or left soles.
- 30 85. In a sole-cutting apparatus, a traveling knife, and a sole-pattern having oppositely inclined peripheral surfaces with which the knife may co-operate in the cutting of right and left soles.
- 35 86. In a sole-cutting apparatus, a traveling knife, a pattern having oppositely inclined peripheral surfaces converging outwardly and with either of which the knife may co-operate during the cutting operation, and means for supporting the pattern and arranged to permit its reversal to present either of the surfaces to the knife for the cutting of right or left soles.
- 40 87. In a sole-cutting apparatus, a traveling knife, a sole-pattern having oppositely inclined peripheral surfaces forming a re-entrant angle and with either of which surfaces the knife may co-operate during the cutting operation, and means for supporting the pattern and arranged to permit its reversal to present either of the surfaces to the knife for the cutting of right or left soles.
- 45 88. In an apparatus for cutting rubber stock, cutting mechanism, opposed pressure members between which the stock is clamped during the cutting operation, telescoping members one of which carries a pressure member, means for reciprocating the other telescoping member, and a plurality of springs interposed between the members and situated outside their telescoping portions.
- 50 89. In an apparatus for cutting rubber stock, a cutting device, a pattern with which the cutting device co-operates, a pressure-plate co-operating with the pattern, a stem extending from the plate, a head having a cylinder surrounding the stem, springs interposed between the head and plate, and a movable operating member acting upon the head.
- 55 90. In an apparatus for cutting rubber stock, a cutting device, a pattern with which the cutting device co-operates, a pressure device co-operating with the pattern, telescoping members one of which carries the pressure device, means for reciprocating the other telescoping member, a rod fixed to one of the members and extending through an opening in the other, and a spring 60 surrounding the rod between the members.
- 65 91. In an apparatus for cutting rubber stock, a cutting device, a pattern with which the cutting device co-operates, a pressure-plate co-operating with the pattern, a stem extending from the plate, a head having a cylinder surrounding the stem, rods fixed to the plate and extending through openings in the head, means carried by the rods for limiting the movement of the head, springs surrounding the rods between the plate and head, and a rotatable cam acting upon the 10 head. 5
- 70 92. In an apparatus for cutting rubber stock, intermittently operating cutting mechanism, a conveyor-belt upon which the cutting operations are performed, means spaced from the belt for advancing the stock to it, means for causing the travel of the belt during the intermittencies of the cutting operations, and means situated above the end of the belt toward the advancing means and in proximity to the cutting mechanism for 15 forcing the stock into engagement with said belt during its travel.
- 75 93. In an apparatus for cutting rubber stock, intermittently operating cutting mechanism, a conveyor-belt upon which the cutting operations 20 are performed, means for causing the travel of the belt during the intermittencies of the cutting operations, an idle roll contacting with the stock above the belt, pivoted arms upon which the roll is rotatable, a spring engaging an arm 25 and forcing the roll toward the stock, and means co-operating with an arm for adjustably limiting the movement of the roll under the influence of the spring.
- 80 94. In an apparatus for cutting rubber stock, cutting mechanism, a table over which the stock is fed, a conveyor-belt receiving stock from the table and having a horizontal run upon which the cutting operations are performed, and a pressure member acting upon the stock over that 30 portion of the horizontal run of the conveyor toward the table. 35
- 85 95. In an apparatus for cutting rubber stock, cutting mechanism, a roll for feeding stock toward the cutting mechanism, a table over which 40 the stock is fed, a conveyor-belt receiving stock from the table and having a horizontal run upon which the cutting operations are performed, and a pressure member acting upon the stock over that portion of the horizontal run of the conveyor 45 toward the table. 50
- 90 96. In a sole-cutting apparatus, a sole-pattern, a cutting device co-operating with the pattern, a carrier for the cutting device, actuating means for the carrier, two driving members one of which 55 exerts its influence to move the actuating means along a predetermined path and the other of which modifies this effect to cause the path to more closely approach the contour of the pattern, and means for modifying the effect of both 60 driving members to bring the path of the connection between the actuating means and carrier into closer agreement with the contour of the pattern.
- 95 97. In a sole-cutting apparatus, a sole-pattern, 65 a cutting device co-operating with the pattern, a carrier for the cutting device, actuating means for the carrier, two driving members one of which exerts its influence to move the actuating means along a predetermined path and the other 70 of which modifies this effect to cause the path to more closely approach the contour of the pattern, and means included in the actuating means and constructed and arranged to modify the effect of both driving members to bring the 75

path of the connection between the actuating means and carrier into closer agreement with the contour of the pattern.

98. In a sole-cutting apparatus, a sole-pattern, 5 a cutting device co-operating with the pattern, a carrier for the cutting device, actuating means for the carrier, two driving members one of which exerts its influence to move the actuating means along a predetermined path and the 10 other of which modifies this effect to cause the path to more closely approach the contour of the pattern, and a member rotatable upon the actuating means and to which the carrier is connected.

99. In a sole-cutting apparatus, a sole-pattern, 15 a cutting device co-operating with the pattern, a carrier for the cutting device, actuating means for the carrier, two driving members one of which exerts its influence to move the actuating 20 means along a predetermined path and the other of which modifies this effect to cause the path to more closely approach the contour of the pattern, a member rotatable upon the actuating means and to which the carrier is connected, and means arranged to vary the point 25 of connection of the carrier to the rotatable member.

100. In a cutting apparatus, a pattern, a cutting device co-operating with the pattern, two 30 rotatable driving members one of which is provided with a slot, a projection movable by the other member and entering the slot, a disk rotatable upon the projection, means for rotating the disk, and a carrier for the cutting device 35 movable upon the disk.

101. In a cutting apparatus, a pattern, a cutting device co-operating with the pattern, two rotatable driving members one of which is provided with a slot, a projection movable by the 40 other member and entering the slot, a disk rotatable upon the projection, means operable by one of the driving members for rotating the disk, and a carrier for the cutting device movable upon the disk.

102. In a cutting apparatus, a pattern, a cutting device co-operating with the pattern, two rotatable driving members one of which is provided with a slot, a projection movable by the other member and entering the slot, a disk rotatable upon the projection, gearing connecting the disk with one of the driving members, and a carrier for the cutting device pivoted upon the disk.

103. In a cutting apparatus, a pattern, a cutting device co-operating with the pattern, two rotatable driving members one of which is provided with a slot, a projection movable by the other member and entering the slot, a disk rotatable upon the projection and having a transverse slot, means for rotating the disk, and a carrier for the cutting device having a pivotal support adjustable along the slot in the disk.

104. In a cutting apparatus, a pattern, a knife co-operating with the pattern, a crank member, 65 an eccentric-disk, means for rotating the member and eccentric-disk, an eccentric-strap movable simultaneously by the crank member and eccentric, a disk rotatable upon the eccentric-strap, and a carrier-arm for the knife pivoted upon the disk.

105. In a cutting apparatus, a pattern, a knife co-operating with the pattern, a crank member, an eccentric-disk, means for rotating the member and eccentric-disk, an eccentric-strap movable simultaneously by the crank member and

eccentric, a disk rotatable upon the eccentric-strap, gearing connecting the eccentric and disk, and a carrier-arm for the knife pivoted upon the disk.

106. In a cutting apparatus, a pattern, a knife 5 co-operating with the pattern, a crank member, an eccentric-disk, means for rotating the member and eccentric-disk, an eccentric-strap movable simultaneously by the crank member and eccentric, a disk rotatable upon the eccentric-strap 10 and having a slot formed across its face at one side of the axis, a pin variable in position along the slot, and a carrier-arm for the knife pivoted upon the pin.

107. In a cutting apparatus, a pattern, a contact-rail supported adjacent to the pattern, an actuating member, an arm pivoted upon the actuating member and revolved thereby about the pattern, a yoke rotatable upon the actuating member, and rolls rotatable upon the yoke 20 and engaging opposite sides of the rail.

108. In a cutting apparatus, a pattern, a knife 25 cooperating with the pattern, means for moving the knife about the pattern and including an eccentric and its strap, a track associated 25 with the pattern, and means carried by the eccentric-strap and engaging the track.

109. In a cutting apparatus, a pattern, a knife 30 cooperating with the pattern, means for moving the knife about the pattern and including 30 an eccentric and its strap, an arm pivoted for movement upon the eccentric-strap and by which the knife is carried, said arm contacting with the eccentric-strap at a point removed from the pivot, a track associated with the pattern, and means carried by the eccentric-strap 35 and engaging the track.

110. In a cutting apparatus, a pattern, a knife 40 cooperating with the pattern, means for moving the knife about the pattern and including 40 an eccentric and its strap, an arm pivoted for movement upon the eccentric-strap and by which the knife is carried, said arm contacting with the eccentric-strap at a point removed from the pivot, a track associated with the pattern, and rolls rotatable upon the eccentric-strap 45 and contacting with opposite sides of the track.

111. In a cutting apparatus, a pattern, a rotatable actuating member, an arm pivoted upon the actuating member, a knife carried by the 50 arm and co-operating with the pattern, a stud secured to the actuating member, a tension-arm rotatable about the stud and connected to the knife-arm, and a spring joined at its opposite 55 extremities to the actuating member and tension-arm.

112. In a cutting apparatus, a pattern, a rotatable actuating member, an arm pivoted upon the actuating member, a knife carried by the 60 arm and co-operating with the pattern, a stud secured to the actuating member, a tension-arm rotatable about the stud and connected to the knife-arm, a spring joined at its opposite extremities to the actuating member and tension-arm, and means arranged to vary the tension of the spring.

113. In a cutting apparatus, a pattern, a rotatable actuating member, an arm pivoted upon the actuating member, a knife carried by the 70 arm and co-operating with the pattern, a casing fixed against movement upon the actuating member, a stud secured within the casing, a tension-arm rotatable about the stud and connected to the knife-arm, and a spring situated within 75

the casing and joined at its opposite extremities to said casing and to the tension-arm.

114. In a cutting apparatus, a pattern, a rotatable actuating member, an arm pivoted upon the actuating member, a knife carried by the arm and co-operating with the pattern, a casing fixed against movement upon the actuating member, a stud secured within the casing, a tension-arm rotatable about the stud and connected to the knife-arm, a spring situated within the casing and joined at its opposite extremities to said casing and to the tension-arm, and means arranged to vary the force exerted upon the arm by the spring.

115. In a cutting apparatus, a pattern, a rotatable actuating member, an arm pivoted upon the actuating member, a knife carried by the arm and co-operating with the pattern, a casing fixed against movement upon the actuating member, a stud secured within the casing, a tension-arm rotatable about the stud and connected to the knife-arm, a spring situated within the casing and attached at one extremity thereto, a member movable upon the stud and to which the opposite extremity of the spring is attached, and means for separably connecting the tension-arm to said member at different points.

116. In a cutting apparatus, a pattern, a rotatable actuating member, an arm pivoted upon the actuating member, a knife carried by the arm and co-operating with the pattern, a casing fixed against movement upon the actuating member, a stud secured within the casing, a tension-arm rotatable about the stud and connected to the knife-arm, a spring situated within the casing and attached at one extremity thereto, a disk rotatable upon the stud and to which the opposite extremity of the spring is attached, said member being provided with series of openings, and a member arranged to secure the tension-arm in one of said openings.

117. In a cutting apparatus, a pattern, a rotatable actuating member, a knife-carrier movable upon the actuating member, a tension member movable upon the actuating member and connected to the carrier to urge the knife toward the pattern, and means engaging the tension member and arranged to hold the knife-arm in an inactive position.

118. In a cutting apparatus, a pattern, a rotatable actuating member, an arm pivoted upon the actuating member, a knife carried by the arm and co-operating with the pattern, means carried by the actuating member and acting upon the arm to normally urge the knife toward the pattern, and a latch arranged for manipulation by the operator to hold the arm upon the actuating member with the knife in an inactive position at any point about the pattern.

119. In a cutting apparatus, a pattern, a rotatable actuating member, an arm pivoted upon the actuating member, a knife carried by the arm and co-operating with the pattern, means acting upon the arm to normally urge the knife toward the pattern, a tension-arm rotatable upon the member, a spring connecting the tension-arm and actuating member, and a latch movable upon the tension-arm and engaging the actuating member.

120. In a cutting apparatus, a pattern provided with oppositely inclined peripheral surfaces, a knife-holder having oppositely inclined surfaces contacting with the inclined pattern-surfaces during the cutting operation, a knife mounted

in the holder, and means for moving the pattern and holder relatively to cut the work.

121. In a cutting apparatus, a pattern provided with oppositely inclined peripheral surfaces, a knife-holder having oppositely inclined surfaces contacting with the inclined pattern-surfaces during the cutting operation, a knife secured in the holder, a movable carrier upon which the holder is mounted, means for revolving the holder about the pattern, and means for moving the carrier to force the inclined surfaces of the holder against the inclined surfaces of the pattern during the revolution of said holder.

122. In a cutting apparatus, a pattern provided with oppositely inclined peripheral surfaces, a rotatable actuating member, a carrier-arm pivoted upon the actuating member, and a knife-holder mounted upon the arm and having oppositely inclined surfaces contacting with the inclined surfaces of the pattern.

123. In a cutting apparatus, a pattern provided with oppositely inclined peripheral surfaces, a rotatable actuating member, a carrier-arm pivoted upon the actuating member, a knife-holder mounted upon the arm and having oppositely inclined surfaces contacting with the inclined surfaces of the pattern, and a spring connecting the actuating member and carrier-arm and drawing the inclined surfaces of the holder and pattern together.

124. In a cutting apparatus, a pattern provided with oppositely inclined peripheral surfaces, a holder movable about the periphery of the pattern and having oppositely inclined surfaces corresponding to those of the pattern, there being spaced surfaces upon the holder furnishing contact with one of the inclined pattern-surfaces, and a knife mounted upon the holder and inclined similarly to the other inclined pattern-surface.

125. In a cutting apparatus, a pattern provided with peripheral surfaces converging outwardly, and a knife-holder movable about the pattern and having surfaces diverging toward said pattern for respective contact with the inclined pattern-surfaces.

126. In a cutting apparatus, a pattern provided with peripheral surfaces converging outwardly, a knife-holder movable about the pattern and having surfaces diverging toward said pattern for respective contact with the inclined pattern-surfaces, and means for drawing the inclined surfaces into engagement during the cutting operation.

127. In a cutting apparatus, a pattern provided with an inclined peripheral surface, a clamping device, means for moving the pattern and device relatively to clamp the work between them, a holder, a knife mounted in the holder and inclined to correspond to the inclined pattern-surface, means for moving the holder about the pattern, and means made effective during the travel of the holder about the pattern for moving the knife toward and from the clamped work in the direction of inclination of the peripheral pattern-surface.

128. In a cutting apparatus, a pattern provided with oppositely inclined peripheral surfaces, means for clamping work against the pattern, a holder having oppositely inclined surfaces for contact with the inclined pattern-surfaces, a knife mounted upon the holder at an inclination corresponding to one of the pairs of contacting surfaces, and means for moving the holder and

knife until they are stopped by contact of the other pair of surfaces.

129. In a cutting apparatus, a pattern provided with an inclined peripheral surface, a carrier revoluble about the pattern, and a knife-holder movable upon the carrier laterally of the pattern and having an inclined surface for contact with the inclined pattern-surface.

130. In a cutting apparatus, a pattern provided with an inclined peripheral surface, a carrier revoluble about the pattern, a knife-holder movable upon the carrier laterally of the pattern and having an inclined surface for contact with the inclined pattern-surface, and means for producing the lateral movement of the holder during such contact to separate the knife from the pattern.

131. In a cutting apparatus; a pattern provided with an inclined peripheral surface, a carrier revoluble about the pattern, and a knife-holder pivoted upon the carrier and movable longitudinally of the pivot, said holder having an inclined surface for contact with the inclined pattern-surface.

132. In a cutting apparatus, a pattern provided with an inclined peripheral surface, a carrier revoluble about the pattern, a knife-holder pivoted upon the carrier and movable longitudinally of the pivot, said holder having an inclined surface for contact with the inclined pattern-surface, and a spring urging the holder upon the pivot away from the work.

133. In a cutting apparatus, a pattern provided with an inclined surface, a carrier revoluble about and movable toward and from the pattern, a knife mounted upon the carrier at an angle corresponding to the inclined pattern-surface and being movable upon the carrier along said inclined surface, and means for moving the carrier away from the pattern.

134. In a cutting apparatus, a pattern provided with an inclined surface, a carrier revoluble about and movable toward and from the pattern, a holder movable upon the carrier toward the pattern, a knife mounted upon the holder at an angle corresponding to the inclined pattern-surface and co-operating therewith, means for normally holding the carrier and holder away from the pattern, and means for moving the carrier toward the pattern during the cutting operation.

135. In a cutting apparatus, a pattern provided with an inclined surface, a rotatable actuating member, a carrier-arm pivoted upon the actuating member, a holder movable upon the carrier-arm, a knife mounted upon the holder at an angle corresponding to the inclined pattern-surface and being movable along said inclined surface by the carrier-arm and by movement of the holder upon said arm, a spring joining the actuating member and carrier-arm and urging the knife toward the pattern, and means for moving the arm away from the pattern against the force of the spring and permitting movement of the holder upon the arm.

136. In a cutting apparatus, a pattern provided with an inclined surface, a carrier revoluble about and movable toward and from the pattern, a knife mounted upon the carrier and being movable upon the carrier along the inclined surface, and means contacting with the pattern for moving the carrier away from said pattern.

137. In a cutting apparatus, a pattern provided with an inclined surface, a carrier revoluble about and movable toward and from the pattern, a knife mounted upon the carrier and being mov-

able upon the carrier along the inclined surface, mechanism for revolving the carrier, and means movable upon the carrier and actuated by the revolving mechanism for moving the carrier away from the pattern.

138. In a cutting apparatus, a pattern provided with an inclined surface, a rotatable actuating member, a carrier-arm pivoted upon the actuating member, a holder movable upon the carrier-arm, a knife mounted upon the holder at an angle corresponding to the inclined pattern-surface and being movable along the inclined surface by the carrier-arm and by movement of the holder upon said arm, a spring joining the actuating member and carrier-arm and urging the knife toward the pattern, a lever fulcrumed upon the carrier-arm and arranged for contact with the periphery of the pattern, and connections between the lever and actuating member for moving the arm away from the pattern against the force of the spring.

139. In a cutting apparatus, a pattern provided with an inclined surface, a rotatable actuating member, a carrier-arm pivoted upon the actuating member, a holder movable upon the carrier-arm, a knife mounted upon the holder at an angle corresponding to the inclined pattern-surface and being movable along said inclined surface by the carrier-arm and by movement of the holder upon said arm, a spring joining the actuating member and carrier-arm and urging the knife toward the pattern, a lever fulcrumed upon the carrier-arm and arranged for contact with the periphery of the pattern, and connections between the lever and actuating member for moving the arm away from the pattern against the force of the spring.

140. A sole-cutting pattern provided with peripheral guide-surfaces oppositely inclined and forming with each other a re-entrant angle, said pattern being arranged for reversal to permit the cutting of either right or left soles.

141. In a cutting apparatus, a pattern provided with oppositely inclined peripheral surfaces forming a re-entrant angle, a knife-holder and knife having oppositely inclined surfaces contacting with the inclined pattern-surfaces during the cutting operation, means for continuously maintaining such contact, and means for revolving the holder about the pattern.

142. In a cutting apparatus, a pattern provided with peripheral surfaces diverging outwardly, and a knife-holder movable about the pattern and having surfaces converging toward said pattern for respective contact with the inclined pattern-surfaces.

143. In a cutting apparatus, a horizontal pattern provided with oppositely inclined peripheral surfaces forming a re-entrant angle, a knife-holder and knife having oppositely inclined surfaces contacting with the inclined pattern-surfaces, the knife being constantly maintained with its point in cutting position below the pattern, and means for elevating the work into cutting relation against the pattern.

144. In a cutting apparatus, a pattern provided with oppositely inclined peripheral surfaces, a holder movable about the periphery of the pattern and having oppositely inclined surfaces corresponding to those of the pattern, there being curved projections formed integrally with the holder close to each other at opposite sides of a vertical plane through the cutting edge of the knife, said projections furnishing contact with one inclined pattern-surface, and a knife mount-

ed upon the holder and inclined similarly to the other inclined pattern-surface.

145. In an apparatus for cutting rubber stock, a pattern, a track associated with the pattern, a knife movable in co-operation with the pattern, knife-actuating means having a portion contacting with the track, an electrical heating unit mounted to move with the knife, and means carried by the track for delivering current to the unit.

146. In an apparatus for cutting rubber stock, a pattern, a track associated with the pattern, a knife movable in co-operation with the pattern, knife-actuating means having a portion contacting with the track, an electrical heating unit mounted to move with the knife, a collector-ring supported upon the track, and a brush carried by the actuating means for contact with the collector-ring and being connected to the heating unit.

147. A sole-cutting machine having a knife, a sole-pattern and a co-operating work-clamping member, one of which is constructed and arranged to function as a work-support and one of which is movable toward and from the other to grip the work, in combination with mechanism for moving the knife round the pattern comprising two concentric shafts, a bevel-gear secured to each shaft, another intermeshing bevel-gear and driving means therefor through which said shafts are rotated in opposite directions, a crank and an eccentric-disk respectively actuated from said shafts, a rotary member constituting an eccentric-strap and actuated simultaneously by said crank and by said eccentric, a carriage for the knife, means tending constantly to move the carriage and the knife toward the pattern and maintain a part of the carriage in contact with the pattern, and a link pivotally connected to both said rotary member and said carriage.

148. A sole-cutting machine having a knife, a sole-pattern and a co-operating work-clamping member, one of which is constructed and arranged to function as a work-support and one of which is movable toward and from the other to grip the work, in combination with mechanism for moving the knife round the pattern comprising a crank and an eccentric-disk, means for rotating them in opposite directions, a rotary member constituting an eccentric-strap and actuated simultaneously by said crank and by said eccentric, a knife-carriage, and a link pivotally connected to both said rotary member and said carriage.

149. A sole-cutting machine having, in combination, a sole-pattern and co-operating work-clamp, a knife, a knife-carriage and mechanism for moving the knife and the carriage round the pattern comprising a crank, an eccentric-disk, means for rotating them, a rotary member including an eccentric-strap having a running fit over said disk and actuated simultaneously by said crank and by said eccentric, and means connecting said member and said carriage.

150. A machine for use in making shoes or shoe-parts having, in combination, a sole-shaped pattern, a tool, a tool-carriage and mechanism for moving them round the pattern comprising a crank, an eccentric-disk and means for rotating them in opposite directions, and an eccentric-strap surrounding the eccentric-disk and having two arms connected respectively to said crank and to said carriage.

151. A machine for use in making shoes or shoe-parts having, in combination, a pattern, a

tool, a tool-carriage, a crank and an eccentric rotating about the same axis, an eccentric-strap having a sliding connection with the crank, means connecting the eccentric-strap and the carriage, and means for rotating the crank and the eccentric to cause the tool to travel in a closed, elongated path round the pattern.

152. A machine for use in making shoes or shoe-parts, having, in combination, a tool, a tool-carriage, a pattern, two concentric, vertical shafts, of which the outer carries a horizontal crank and the inner carries an eccentric immediately adjacent to the crank, an eccentric-strap having a pin-and-slot connection with the crank, and means connecting the eccentric-strap and the carriage for moving the tool round the pattern.

153. A rubber-sole-cutting machine having, in combination, a sole-shaped pattern, a clamp, means for relatively moving the pattern and clamp to grip work placed between them, a knife, a knife-carriage, means for maintaining the knife in predetermined relation to the edge of the pattern, and means by which the knife may be moved longitudinally of itself on the carriage while the work is so gripped to cause the knife to penetrate the work.

154. A rubber-sole-cutting machine having, in combination, a sole-pattern, a clamp including a work-engaging sheet of flexible, penetrable material projecting beyond the edge of the pattern, and means including a plurality of sheet-engaging members for exerting a yielding pressure upon said sheet over substantially the entire marginal area of the pattern to clamp the work to the pattern.

155. A rubber-sole-cutting machine having, in combination, a pattern, a clamp including a work-engaging sheet of moderately flexible, penetrable material projecting beyond the edge of the pattern, a series of independent, spring-pressed bars acting upon said sheet, and means for moving said clamp to grip work placed between said pattern and said clamp so as to exert a clamping pressure upon the work over substantially the entire marginal area of the pattern.

156. In a cutting machine, a pattern, a knife, means for urging the knife yieldably into co-operation with the pattern, two driving members rotatable about a common axis, one of said members being provided with a slot extending radially with respect to the axis, a pin movable by the other member and entering the slot for actuating engagement by a wall thereof, a carrier for the knife, and connections to the pin for actuating the knife.

157. In a cutting machine, a pattern, a knife co-operating with the pattern, two driving members rotatable about a common axis, one of said members being provided with a slot extending radially with respect to the axis, an actuating member surrounding the axis of rotation and movable by the other driving member, said actuating member having a projection entering the slot in the driving member, a carrier for the knife, and connections to the actuating member for moving the carrier and knife about the pattern and for drawing the carrier and knife into co-operation with said pattern.

158. In a cutting machine, a pattern, a knife co-operating with the pattern, a crank member, an eccentric-disk, means for rotating the member and disk in opposite directions, an eccentric-strap movable simultaneously by the crank member and eccentric, a carrier for the knife, and

connections between the carrier and strap, said connections including a pivotal mounting for the carrier.

159. In a cutting machine, a pattern, a knife co-operating with the pattern, two shafts, means for rotating the shafts in opposite directions, a crank member and an eccentric-disk respectively actuated from the shafts, an eccentric-strap movable simultaneously by the crank member and eccentric, a pivot-pin movable by the strap, and an arm pivoted upon the pin and carrying the knife.

160. In a cutting machine, a pattern, a knife co-operating with the pattern, a crank member, an eccentric-disk, means for rotating the member and disk in opposite directions, an eccentric-strap movable simultaneously by the crank member and eccentric, a carrier for the knife, connections between the carrier and strap, said connections including a pivotal mounting for the carrier, and means connecting the strap and carrier for urging the knife toward the pattern.

161. In a cutting machine, a pattern, a knife co-operating with the pattern, two shafts, means for rotating the shafts in opposite directions, a crank member and an eccentric-disk respectively actuated from the shafts, an eccentric-strap movable simultaneously by the crank member and eccentric, a pivot-pin movable by the strap, an

arm pivoted upon the pin and carrying the knife, and a spring mounted upon the strap and connected to the arm.

162. In a cutting machine, a pattern, a clamp, means for moving the pattern and clamp relatively to grip work between them, a knife-carrier, a knife movable by the carrier about the pattern, means arranged to move the knife longitudinally of itself away from the clamped work, and means for retaining the knife in cutting position against the force of the moving means.

163. In a cutting machine, a pattern, a knife co-operating with the pattern, a clamp co-operating with the pattern to grip the work, said clamp comprising a plurality of independently yieldable pressure members, and means for moving the clamped work and knife relatively to cut the work about the pattern.

164. In a cutting machine, a fixed support, a pattern secured to the support, a rotatable actuating member, an arm pivoted upon and revoluble by the actuating member, and a knife-carriage pivoted upon the arm and provided with three contact-portions spaced from one another and arranged for engagement with the edge of the pattern, the line of contact of one of said portions being in substantial alignment with the pivotal axis of the carriage.

ERNEST W. STACEY.
